UNITED STATES PATENT OFFICE.

EDWIN H. SMYTHE, OF EVANSTON, ILLINOIS, AND SAMUEL B. WILLIAMS, JR., OF BROOKLYN, NEW YORK, ASSIGNEES TO WESTERN ELECTRIC COMPANY, INCORPORATED, OF NEW YORK, N. Y., A CORPORATION OF NEW YORK.

HIGH-FREQUENCY SIGNALING AND COMMUNICATING SYSTEM.

Application filed May 5, 1920. Serial No. 379,105.

To all whom it may concern:

Be it known that we, EDWIN H. SMYTHE and SAMUEL B. WILLIAMS, Jr., citizens of the United States, residing at Evanston, in the county of Cook and State of Illinois, and at Brooklyn, in the county of Kings and State of New York, respectively, have invented certain new and useful Improvements in High-Frequency Signaling and Communicating Systems, of which the following is a full, clear, concise, and exact description.

This invention relates to an improved communicating system, and more particularly to a communicating system of the type in which the control of switching mechanism and the establishment of communicating circuits are automatically effected through the medium of high frequency electrical oscillations, either transmitted through space in the form 20 of electromagnetic waves or guided upon metallic conductors.

This invention is directed particularly toward increasing the number of stations that may be served in an automatic system of intercommunication by a limited number of non-interfering carrier waves, or high frequency channels over which such waves are transmitted and received. Heretofore, in systems of this character, it has been customary to provide as many such high frequency communication channels as there were stations to be served, each channel being normally identified with a particular station as the means of access thereto. In the present system, only as many channels need be provided as the maximum number of simultaneously existing connections between stations, the number of channels therefore being only a relatively small percentage 40 of the number of high frequency stations for which intercommunication is to be provided. In accordance with this invention, any one of a relatively large number of high frequency stations in the communicating system 45 has access to and may use any one that happens to be idle of a relatively small number of high frequency carrier waves or communicating channels.

To this end, and to the end of realizing a number of other incidental advantages, it is the object of the present invention to provide a system in which a plurality of high frequency channels are made available for use by a plurality of stations; in which any high

frequency station may have the use of any 55 one of the channels in establishing communicating or operative relation with any other high frequency station; in which a relatively large number of stations, one or more of which may be associated with each of a number 60 of groups of local stations, may be served by a relatively small number of communication channels; in which each station, in calling, automatically tests the intercommunication channels that are provided and automatically selects one of these channels which is not at the time in use; in which the selected channel is appropriated by the calling station and is guarded against selection for use by any other station; in which means are 70 provided for preventing two or more calling stations from performing their channel testing and selecting operations simultaneously; in which a channel is normally provided for the common use of all of the stations, through 75 which channel the stations that are not communicating with each other are normally in operative relation; in which the use of this common channel by any calling station automatically prevents its employment by any 80 other station that calls while the channel is in use; in which means are provided for enabling the calling station, preferably through the medium of the common calling channel, to select the station with which 85 communication is desired, and to exclude the other idle stations that are not being called; in which means are provided for registering at the calling station the particular channel that that station selects for use in establishing its connection; in which means are made operative upon the selection of the called station for tuning both the calling and the called station, under the control of the channel registering apparatus, to the particular 90 channel that has been selected for use; in which the tuning of the calling and called stations to the selected communicating channel 95 frees the common calling channel for use by other calling stations in setting up their 100 connections; in which each of the communicating channels may consist of a pair of high frequency carrier waves, while the common calling channel consists of a single high frequency wave, in which means are provided 105 for automatically tuning each station for the transmission of a particular one of the waves of a pair and the reception of the other wave

2
of the pair depending upon whether the station is the calling station or the called station; in which means are provided for enabling one station to control the tuning of 5 another station for the transmission and reception of particular carrier waves or pairs of carrier waves; in which means are provided for preventing the release of the connection between two communicating stations 10 from bringing those stations into operative relation with the common calling channel if the release occurs while the calling channel is in use; in which local lines associated with each high frequency station are prevented 15 from obtaining access to the associated station while the station is in use either as a calling or as a called station, or when any other station of the system is using the common calling channel in setting up a connection; and in which means are provided for 20 effecting the production of a busy signal and the release of a connection when the complete establishment of the connection is for any reason prevented. The foregoing are some 25 of the principal objects that the system of the present invention attains. In addition the system embodies a number of other features incidental to those mentioned above, and incidental to its use as a part of a 30 comprehensive system providing for automatic interconnection and intercommunication between the local stations associated with any of the high frequency stations of the system and the local stations associated with 35 any other of the main stations. The manner in which the foregoing desirable objects and features are realized will be explained in the description that follows of the preferred embodiment of the system, and the structures 40 through which the objects are attained will be more particularly defined in the appended 45 claims.

The preferred embodiment of the invention is illustrated in the accompanying drawings, in which Figs. 1 to 6 inclusive show 45 diagrammatically as much of the circuit organization as is necessary to enable the invention and the preferred manner of practicing it to be understood, and in which Fig. 50 7 is a schematic representation of the general plan of the system.

In assembling Figs. 1 to 6 of the drawing to show the circuit organization, they are to 55 arranged as indicated in Fig. 8.

Referring first to Fig. 7, this illustrates 60 schematically a number of stations, R to R⁴, each having associated with it a number of local stations, S to S⁴ inclusive.

These stations are indicated in the present 65 instance as radio stations, that is, stations between which interconnection and intercommunication is established through the medium of unguided high frequency waves transmitted through space. In the specification 70 that follows the high frequency stations

will frequently be referred to as radio stations; but it is to be understood that the use of this term is not intended to limit the invention to exclude a system the stations of which are operatively related through the 70 medium of high frequency waves guided upon conductors, as the stations of the organization disclosed may be of this character. Each high frequency or radio station is represented as being provided with conductive 75 means for establishing connection between it and any of its local stations, and with radio or high frequency oscillation means for establishing communication between it and any of the other radio stations of the system. 80 The radio communicating means of each of the radio stations are represented in the schematic drawing to comprise, in the present instance, a transmitting antenna TA and a separate receiving antenna RA. The medium of communication between the different high frequency stations is indicated to consist of high frequency oscillations either transmitted freely through space or guided 85 over a metallic conductor; and in the present 90 instance these are represented by the broken line circles X to X⁴ inclusive. The broken line circle X is intended to represent the single carrier wave that is used as a common or calling carrier wave; and the four pairs of broken line circles X' to X⁴ inclusive are intended to represent four pairs of carrier 95 waves any pair of which is available for non-interfering communication between any two of the stations of the system. The normal 100 availability of the common or calling carrier wave X to all of the idle or non-busy stations R is represented by the broken lines which radiate from this circle to the receiving antennæ RA of all of the non-busy stations. 105 At the station R' the common or calling carrier wave X is connected with the transmitting antenna TA to indicate that the station R', as a result of the call from its local 110 station S², has appropriated the calling wave and is using it to effect the selection of one of the other radio stations the receiving antennæ RA of which are responsive to the calling wave. The receiving antennæ RA of the calling station R' is represented by the 115 arrow-headed broken line to be in condition where it is testing for an idle one of the communicating carrier waves X' to X⁴ inclusive. The first two of the four pairs of carrier 120 waves are represented as being in use, the pair X' being in use in establishing operative relation between local station S of radio station R and local station S³ of radio station R', and the second pair X² being represented 125 as being in use in establishing connection between local station S' of radio station R¹ and local station S of radio station R². This condition of use, as will subsequently be explained, renders the two pairs of waves X' and X² unavailable for use by the call 130

ing radio station R'. The calling station therefore, as will be explained, selects for use one of the two idle pairs X³ and X⁴ which are represented by the lighter broken 5 lines.

As has been stated, Fig. 7 is merely an attempt to illustrate schematically the general idea or plan of arrangement of the system, and does not pretend to show anything more 10 than this. Furthermore, the invention contemplates such multiplication of the parts or elements indicated in Fig. 7 as may prove desirable in practice. There may be a larger or smaller number of radio or high frequency stations employed; and each station 15 may have a larger or smaller number of associated local stations, or, if desired, the communicating apparatus supposed to be represented at one of the local stations may 20 be located at and form part of the associated high frequency station itself. There may also be any desired number of communicating channels, such as the pairs of carrier waves, employed for taking care of the traffic 25 for which provision is to be made between the various high frequency stations of the system. For the sake of simplicity any station, such as S, is represented in Fig. 30 7 as having access to only one radio trunk, such as that terminating in the radio station R, but it will be described later on in the more detailed account of the circuits and their operation how such a station S has a 35 second-choice access to another radio trunk, such as that terminating in the radio station R', in case the trunk at station R happens to be busy at the time with another communication.

Referring now to the preferred circuit organization as illustrated in Figs. 1 to 6 inclusive of the drawing, only as much of wiring of a single high frequency station or trunk and its associated local stations is 40 shown as is necessary to enable the invention to be understood; it being possible for one skilled in the art, by mere extension and duplication of the wiring and apparatus illustrated, to organize a system of such capacity as may be desired. As illustrated in 45 the circuit diagram, there is a high frequency station or trunk RT with two associated local stations S and S'. The high frequency station or trunk is provided with a high frequency terminal consisting in the 50 present instance of the transmitting antenna TA and the receiving antenna RA; and also with certain conductive terminals, such as the spring jack 14, the passive terminals of 55 automatic switches such as the selector switch indicated at 4, and the active terminals of an automatic line switch indicated at 13. At the spring jack terminals 14 of the high frequency or radio trunk a connecting cord may be connected with the 60 trunk by means of the plug 15, the connect-

ing cord being provided with the usual equipment including a calling dial 15'. When the radio trunk is being used as an outgoing trunk for calls originating in the associated local stations, as S, S', the local 70 lines are connected with it through the medium of the line switch 2, and thence by way of the trunk 3 and the selector switch 4. The line switch 2 may be of the type commonly known as the Keith line switch, and 75 the selector switch 4 may be a selector switch of the Strowger type, the associated circuits for the control of these switches being of the sort ordinarily used; or any other of the well known arrangements used in the telephone art for extending the connection of a telephone line to the central office apparatus 80 may be substituted. When the radio trunk is used as an incoming trunk for the extension to one of the local lines of a call originating at some other high frequency station, the circuit of the trunk is extended through 85 the medium of a line switch 13 and a connector switch 41, these switches being conveniently of the type and having the wiring 90 arrangement of the switches referred to above.

It is customary in the art to make a distinction between automatic systems, the switches of which are controlled from a subscriber's substation, and systems in which manual substations may be connected to an automatic system through the medium of an operator's cord circuit, such as that shown having associated with it automatic 100 switch-controlling means. The former type is called a full automatic system and the latter type, a semi-automatic system. The present invention is equally well adapted to be used in connection with either a full automatic or a semi-automatic system and has 105 been illustrated as having the necessary connections for both types.

The radio terminals of the trunk may consist of two antennæ TA and RA. These 110 antennæ may be of any desired form, and should preferably be located at a sufficient distance apart to insure the selectivity of the receiving antenna with respect to the energy in the wave radiated by the transmitting antenna; or, if it is desired to locate the antennæ closer together, power limiting devices may be used; or the irresponsiveness of the receiving antenna to the energy it receives from the transmitting antenna may 115 be attained by any of the several methods that are available in the art.

The medium that is employed in the present instance for effecting radio or high frequency communication between the transmitting antenna TA and the receiving antenna, such as RA, of the distant radio station, is a high frequency carrier wave, the oscillatory current for producing which is generated in the tuned high frequency oscil- 120 125 130

1
5 lator 171. The oscillator circuit may be of well known type, comprising a vacuum tube or thermionic oscillator with an oscillation circuit including inductively related inductances in the input and output circuits of the tube. The filament current for this oscillator and for the energization of the other oscillators and for the modulator and power amplifier of the transmitting antenna system is supplied by the filament current generator 148, and the plate current for these devices is supplied by the plate current generator 147. These generators are driven by the motor 146, the current supply 10 for operating which is controlled by the relays 199, 200 and 220.

20 The carrier wave produced by the high frequency oscillator 171 carries two intermediate frequencies, one of these intermediate 25 frequencies being generated by the oscillator 160 and the other being generated by the oscillator 168. Both of these are vacuum tube oscillators and have oscillation circuits of the same type as the carrier wave 30 frequency oscillator 171 referred to above. The intermediate frequency oscillatory currents generated by the oscillator 160 are modulated by the voice currents transmitted 35 from the telephone transmitter of the associated local station. The voice currents from the associated local station pass over the talking conductors 97 and 98 of the trunk and through the four equal windings of the two-way repeating coil 149 into the bal- 40 ancing network 150. The junction points of the two serially included repeating coil windings in each side of the line circuit are connected with the input circuit of a thermionic amplifier 151, and the output circuit 45 of the amplifier is connected by way of the inductive couplings 152 and 154 with the input circuit of the modulator 155.

50 The operation of the oscillating and modulating circuits herein disclosed, is briefly as follows: The oscillator 160 and modulator 155 are supplied with plate current through the choke coil 161 which has sufficiently large inductance to prevent the passage therethrough of current fluctuations 55 of frequencies as high as those used in transmission of speech. The plate current supply circuit for the oscillator 160 contains also a choke coil 159 which transmits voice frequencies but has sufficient inductance to prevent the passage of current fluctuations corresponding to the frequency of oscillator 160. Since the current supplied to the tubes 155 and 160 together in parallel 60 is maintained constant whereas the current through the tube 155 alone is controlled by the impressed voice current, the current through the oscillator 160 is made to vary in a complementary manner, and therefore 65 the amplitude of the wave generated by the oscillator 160 varies in accordance with

70 voice currents received over the line conductors. The frequency of oscillator 160 is controlled by the condenser 157, while the condenser 156, which is too large to have an appreciable effect on the period of the 75 oscillator, serves to prevent short-circuiting of the current supply.

80 The oscillators 160, 168 and 171 are all connected to and feed into the input circuit of the modulating tube 180. Condenser 85 178 affords a high frequency by-pass for the radio frequency current from oscillator 171. The output coils from oscillators 160 and 168 are in series. However, the coupling of the oscillator circuits to the common work circuit may be made sufficiently loose to prevent reaction of one oscillator upon another and to prevent the constants 90 of the work circuit from affecting the period of the oscillator.

95 The action of the modulator 180 is somewhat different from that of 155 since all of the waves are impressed upon the grid circuit and the modulating action depends upon the variation of the tube impedance to the passage of the radio frequency current under control of the currents impressed from oscillators 160 and 168. The result is that the radio frequency wave is modulated by each of the waves from the intermediate frequency oscillators each of which is, in turn, modulated or controlled by currents or waves of lower frequencies. The plate current circuit of the oscillator 160 and modulator 155 is controlled by contacts of 100 a relay 215, so that the intermediate frequency generated by the oscillator 160 may be applied to or withdrawn from the carrier wave to produce signaling impulses. The operation of the other intermediate 105 frequency oscillator 168 is controlled at the contacts of the relay 216 and is applied to the carrier wave for the purpose of guarding against the production by any other station of the particular frequency that is being transmitted by the oscillator 171. The intermediate frequency produced by the oscillator 168, therefore may be referred to as the guarding intermediate frequency and that produced by the oscillator 160 as the 110 signaling and talking intermediate frequency.

115 The output circuit of the modulator 180 is inductively coupled with the tuned input circuit of a power amplifier 209 of the thermionic type; and the output circuit of the amplifier is inductively coupled with the tuned transmitting antenna TA of the system. The tuning of the amplifier input circuit and of the transmitting antenna TA, as 120 well as of the oscillating circuit of the carrier wave oscillator 171, is accomplished 125 through the medium of a plurality of branches, each under the control of a relay. In the embodiment of the invention here 130

disclosed there are seven tuning branches associated with the high frequency oscillator, seven associated with the power amplifier, and seven associated with the transmitting antenna. The seven tuning branches associated with the high frequency oscillator include adjustable condensers 174, 175, 176, 177, 275, 276, and 277, and these branches are respectively controlled by relays 181, 182, 183, 184, 282, 283 and 284. The tuning branches associated with the power amplifier include adjustable condensers 195, 196, 197, 198, 296, 297 and 298, and these branches are respectively controlled by relays 191, 192, 193, 194, 292, 293 and 294. The tuning branches associated with the transmitting antenna include adjustable tuning inductances 211, 212, 213, 214, 312, 313, and 314, and the branches are respectively controlled by relays 201, 202, 203, 204, 302, 303 and 304. For effecting the operation of the relays controlling the tuning branches there are seven energizing circuits, and each of these energizing circuits is connected with the windings of three of the controlling relays, one from each of the three tuning groups. The seven energizing paths or conductors are designated 272, 94, 95, 96, 162, 163 and 164, the first of these conductors being connected with the winding of the first relay in each of the three groups in the order in which these relays were mentioned, the second conductor with the winding of the second relay in each group in the order mentioned, and so on. Thus when any one of the energizing paths is closed, the corresponding relay in each of the three tuning groups is operated, and a corresponding tuning branch in each of the three groups is closed.

The capacities and inductances included in the seven branches of each of the three tuning groups are so adjusted that the closure of any one of the seven energizing paths, with the consequent closure of the corresponding tuning branch in each of the three groups, causes the production and application to the transmitting antenna of an oscillation having a frequency differing from the frequency produced when any other one of the seven energizing paths is closed. In the present instances the frequency of the carrier wave oscillations thus applied to the transmitting antenna may conveniently have the following ratios: 100, 150, 225, 275, 350, 425 and 475, these frequencies being applied by the energization of conductors 272, 94, 95, 96, 162, 163 and 164, respectively.

In the radio receiving part of the system, the receiving antenna RA of each station is inductively coupled with the tuned input circuit of the thermionic detector 230. The output circuit of the detector includes serially the two frequency filters 235 and 236; and also has bridged across the filament and

plate circuit a condenser 237 for eliminating the unmodulated carrier frequency. The filter 235 has its constants so adjusted as to select the guarding intermediate frequency and to by-pass the signaling and talking intermediate frequency, and the filter 236 is adjusted to select the signaling and talking intermediate frequency and to by-pass the guarding intermediate frequency. The filter 236 is inductively coupled with the input circuit of the detector 255, and the output circuit of the detector 255 is inductively coupled with the input circuit of the amplifier 259. The output circuit of the amplifier has two branches controlled in switching contacts of the relay 271. The normally closed branch is connected by way of the inductive coupling 263 with a circuit including two windings of the two-way repeating coil 149. The inductive relation of these two windings with the other windings of the repeating coil 149 is such that the voice currents flowing in the circuit of this branch are repeated into the trunk talking conductors 97 and 98 connected with the other windings of the repeating coil, but are not repeated into the branch connection of the repeating coil with the transmitting amplifier 151. As a result of this arrangement, which is well known in the art, the voice current modulations that reach the called station through its receiving antenna are prevented from re-acting upon the radio transmitting system of that station and causing similar voice current modulations of the oscillatory currents passing to its transmitting antenna. The other branch of the amplifier output circuit, closed when relay 271 is operated, is connected through the inductive coupling 264 with the rectifier 269, and the circuit of the rectifier includes the winding of relay 268. The relay 268 is adapted to respond to the signaling and talking intermediate frequency of the carrier wave, and to act through the medium of conductor 35 to govern the operation of certain switching mechanism of the associated trunk.

The filter 235, which selects the guarding intermediate frequency of the carrier wave, is connected with the input circuit of the thermionic detector 238, and the output circuit of this detector is inductively coupled with the input circuit of the amplifier 245, the output circuit of which in turn is inductively coupled with the circuit of the rectifier 251. The circuit of the rectifier includes the winding of relay 252, which relay is thus adapted to respond to the guarding intermediate frequency of the carrier wave and to act through the medium of conductor 100 to govern the operation of switching mechanism of the associated trunk.

The tuning of the receiving antenna system of the radio trunk is effected, in the

particular embodiment of the invention illustrated, by means of seven branches including the adjustable condensers 231, 232, 233, 234, 332, 333 and 334, respectively. 5 These branches are under the control of relays 221, 222, 223, 224, 322, 323 and 324, respectively. The tuning branch containing the condenser 231 and controlled by relay 221 is normally closed, and the other 10 branches are normally open. The winding of relay 221 is included in a common portion of an energizing circuit having the six branches 42, 43, 44, 165, 166 and 167, and the windings of the other six tuning 15 control relays are included one in each of these six branches. Therefore when any one of the six branches is closed to operate the included relay and close the corresponding tuning branch, the relay 221 is operated to 20 open the normally closed tuning branch that it controls.

The common portion of the energizing circuit that includes the winding of relay 221 also includes the winding of a relay 220 which, when it is operated, closes the energizing circuit of the motor 146 for driving the generators 147 and 148 to produce the plate and filament current, and also closes the circuit of relay 216 to energize 30 the guarding intermediate frequency oscillator 168. Thus the transmitting antenna system is energized to produce the carrier wave and apply the guarding intermediate frequency whenever any one of the six normally open tuning branches of the receiving 35 antenna circuit is closed. It may also be noted that the relay 200 included in the first tuning branch of the transmitting antenna system circuit is operated when that 40 branch is closed to energize the devices for applying the carrier wave and its guarding intermediate frequency; and that when any other one of the seven tuning branches of the transmitting system is closed, the relay 45 199 is operated to break the energizing path by way of relay 200 and at the same time to continue the application of the carrier wave with both its guarding intermediate frequency and its signaling and talking intermediate frequency.

As has been stated, the first tuning branch of the receiving antenna system is normally closed, and the first tuning branch of the transmitting antenna system is closed by the 55 completion of a circuit by way of conductor 272 upon the seizure of the radio trunk by a calling local station, and at certain other times in the operation of the system, as will subsequently be described. The other six 60 tuning branches of the receiving antenna system and the other six branches of the transmitting antenna system are selectively energized under the control of the tuning selector switch P. When the radio station 65 is calling, one or another of the transmitting

system tuning branches 94, 95 and 96, and one or another of the receiving system tuning branches 42, 43 and 44 are energized, depending upon whether the switch P is moved to its first, second or third position 70 from normal. When the radio station is being called, one or another of the transmitting system tuning branches 162, 163 and 164, and one or another of the receiving system tuning branches 165, 166 and 167 are 75 energized, depending upon the position to which the switch P has been moved. The arrangement is such that when the station is calling and the switch P has been moved to its first position from normal, the transmitting system is tuned, in the present instance, to a wave length of 150 meters and the receiving system is tuned to a wave length of 225 meters; while at the same time 80 a corresponding movement of the tuning selector switch P at the called station to its first position from normal causes the transmitting system of the called station to be tuned to a wave length of 225 meters and the receiving system at that station to be tuned to a wave length of 150 meters. Thus it will be seen that in this case the receiving system of the called station is tuned to the carrier wave length of 150 meters that the calling station is transmitting, and that the transmitting system of the called station is tuned to a carrier wave length of 225 meters that the receiving system of the calling station is tuned to receive. In like manner 90 when the switches P at the calling and called stations occupy corresponding positions, the transmitting system of each station is tuned to send out a different carrier wave length to which the receiving system of the other station is tuned to respond. This arrangement may be tabulated as follows:

Switch P.	Calling station.		Called station.	
	Transmitting wave length.	Receiving wave length.	Transmitting wave length.	Receiving wave length.
	Meters.	Meters.	Meters.	Meters.
Position 1.....	150	225	225	150
Position 2.....	275	350	350	275
Position 3.....	425	475	475	425

Additional sets of carrier wave lengths corresponding to additional positions of the switch P may, if desired, be provided by adding other tuning branches to the transmitting and receiving antenna systems of the stations; and these branches may be arranged and controlled similarly to the arrangement and control of the branches that are illustrated. By bringing their switches P into corresponding positions, any calling station and the station that is being called may use for communicating purposes any of these sets of wave lengths. The wave length 130

to which the receiving systems of all of the radio stations are normally tuned may be, for instance, 100 meters and the transmitting systems of all of the radio stations are 5 adapted normally to send out this wave. The carrier wave lengths that have been referred to above are merely typical, as any desired combination of wave lengths may be used, provided only that the frequencies selected 10 are non-interfering.

The apparatus which is used to transmit and receive by means of any one high frequency wave as distinguished from that which is used only when a wave of a different frequency is employed, is commonly known as a channel or a high frequency communication channel. It will be seen that each terminal apparatus is capable of transmitting or receiving through any one of a 15 number of channels and that one such channel may be selected and appropriated for use by a pair of stations, to the exclusion of all other stations of the system and that the channels, by virtue of the different frequencies which they employ respectively, do not interfere with one another, but enable independent simultaneous communication between different stations of the system.

As has been stated, the system is so arranged that each carrier wave may have applied to it two intermediate radio frequencies, one of which is modulated to carry the speech frequencies and also is applied and withdrawn to convey the signaling and 30 switch controlling impulses, and the other of which is modulated or controlled to guard against simultaneous use by some other station of the carrier wave to which it is applied. These intermediate frequencies may 35 have any desired value above the audio frequency and below the carrier wave frequency range. For example, the talking intermediate frequency may be twenty thousand and the guarding intermediate 40 frequency may be fifty thousand. These two intermediate frequencies may be the same for all of the carrier waves employed, as the non-interference between simultaneously communicating pairs of radio stations 45 is ensured by the non-interfering carrier wave lengths that are employed.

Each radio trunk has associated with it receiving register switch apparatus and transmitting register switch apparatus employed when the associated radio station is calling another radio station, and additional receiving register switch apparatus and transmitting register switch apparatus employed when the associated radio station is 50 being called by some other radio station. The calling receiving register switch apparatus consists of a station receiving register switch A, a carrier wave receiving register switch D, a tens receiving register 55 switch B, and a units receiving register

switch C. The calling transmitting register switch apparatus consists of a station transmitting register switch E, a carrier wave transmitting register switch G, a tens transmitting register switch K, and a units transmitting register switch M. Each of these transmitting register switches has associated with it a change-over switch, F, H, I, and N, respectively, for interposing an interval between the operation of the 60 associated switch and the operation of the next switch in the series. The receiving register apparatus that comes into use when the radio station is called by another radio station comprises a station receiving register switch or station selecting switch AR, a carrier wave receiving register switch V, a tens receiving register switch BR, and a units receiving register switch CR. The transmitting register apparatus that becomes active when the radio station is called by some other radio station comprises a tens transmitting register switch W and a units transmitting register switch Z. Each 65 station also has a tuning switch P, that operates when the station is the calling station to tune the transmitting antenna and receiving antenna systems to the pair of carrier waves registered by the carrier wave receiving register switch D; and which operates when the station is the called station to tune the transmitting and receiving antenna systems to the pair of carrier waves indicated by the carrier wave receiving register switch V. There is also 70 at each station a switch Y that operates to apply a return signal for a pre-determined length of time to the transmitting antenna system at the called station and then withdraw it. All of the switches referred to 75 above may be, and in the present instance are, single motion step-by-step switches, the wipers or switch arms of which are advanced step-by-step by means of an associated stepping magnet, the return of the 80 switch arms to normal being brought about by further energizations of the associated stepping magnets that cause the arms to continue their movement over their rows of contact points until they again rest in their 85 normal position. Such step-by-step switches are well known in the art and need not be particularly described.

Associated with the radio trunk in the form in which it is herein disclosed are also a number of plunger relays, as 73, 79, 46, 52, 62, 101, 118, 127 and 136, which are employed to introduce relatively large time intervals into the operation of certain parts of the organization. The plungers of these 90 relays are retarded in their inward movement and are permitted to move freely on their return movement. They may be of the type disclosed in the application of Samuel B. Williams, Jr., and Walter P. 95

Albert, Serial Number 146,671, filed February 5, 1917.

Briefly stated, the operation of the particular embodiment of the system here disclosed is as follows: When a subscriber wishes connection with another subscriber whose station must be reached through a radio trunk, the taking of his telephone receiver from its hook causes his line switch 10 to extend the circuit of his line to a selector switch; and this switch is operated in response to the first transmitted group of impulses to bring its switch wipers into engagement with the terminals of the first of 15 the radio trunks that may be provided for serving the local stations of this exchange group. If the radio trunk is in use either in establishing an outgoing connection to some other radio station or in establishing 20 an incoming connection from such a station, or if some other radio station is using the common or calling carrier wave to extend a call, there is a busy test potential on the terminals of the trunk, and the selector switch is prevented from making connection 25 with the trunk and proceeds to the next trunk. If the trunk is not in use, the selector switch establishes connection with the trunk terminals, and the trunk is energized 30 to send out the common or calling carrier wave with its guarding intermediate frequency. The second movement of the dial at the subscriber's station sends a group of 35 impulses for determining the distant radio station to which the connection is to be extended, and the third and fourth movements of the dial produce impulses in accordance with the tens and units digits of the local line with which connection is desired at the 40 called radio station. The groups of impulses produced by the second, third and fourth movements of the calling station dial are recorded respectively upon a station receiving 45 register switch, a tens receiving register switch and a units receiving register switch.

Immediately upon the seizure of the radio trunk by the calling subscriber's line, the calling radio station proceeds automatically to tune its receiving antenna system to one 50 after the other of the pairs of individual or communicating carrier wave frequencies. If the pair of individual carrier waves tested is in use, the response of the receiving antenna system of the calling station causes 55 it to be tuned to the next pair of individual carrier waves. If all of the pairs of individual carrier waves happen to be in use, a busy tone is transmitted to the calling subscriber's station, and the connection is 60 released when the calling subscriber hangs up. If one of the pairs of individual carrier waves is found not in use, the identity of the available pair of carrier waves is recorded upon a carrier wave receiving register switch, the receiving antenna system of

the calling radio station is again tuned to the common or calling carrier wave frequency, and the transmitting antenna system of the calling radio station proceeds to send out impulses upon the signaling intermediate frequency of the common or calling carrier wave corresponding in number to the impulses recorded upon the station receiving register switch.

At each radio station of the system that is 75 not in use, the impulses of this group cause the corresponding advance of a station selecting switch. Each of these station selecting switches is arranged to bring its associated station switching apparatus into 80 operative relation with its receiving antenna system only when the switch is advanced to a particular point by the impulses received from the calling radio station; and this point differs with the station selecting 85 switches of the different radio stations, so that for a certain number of impulses transmitted from the calling station over the common carrier wave one only of the other radio stations is placed in operative relation 90 with the calling station at the end of the station selecting impulses. All of the other stations are left inoperative and unresponsive to the succeeding groups of impulses, and are returned to operative condition only 95 when the common carrier wave is withdrawn at the end of the calling operation.

When the sending of the station selecting group of impulses is concluded, the calling radio station withdraws for a predetermined 100 interval the signaling intermediate frequency from the common carrier wave, but continues to apply the wave with its guarding intermediate frequency, and also causes the calling station receiving antenna system 105 during this interval to be responsive to the signaling intermediate frequency of the common carrier wave. At the same time, and during the same interval, the called radio station if it has been selected applies the 110 common carrier wave with its signaling intermediate frequency. As a result, if the called radio station is available, and has responded to the signaling impulses sent from the calling station, it sends out the common or calling carrier wave with its signaling intermediate frequency as a return signal; and the receiving antenna system of the calling radio station responds to this return signal 115 and releases its apparatus to proceed with the next stage of the operation. If the calling station does not receive this return signal within a predetermined time interval, it applies a busy tone to the calling subscriber's line, and the connection is released 120 upon the hanging up of the calling subscriber's telephone receiver. When the called radio station has sent its return signal, it withdraws the common carrier wave 125 with its signaling intermediate frequency 130.

and remains responsive to the common carrier wave with its guarding intermediate frequency that the calling radio station has continuously sent out, so that if for any reason 5 the calling radio station fails to receive the return signal and consequently releases the connection, the withdrawal of the common carrier wave with its guarding intermediate frequency causes the called radio 10 station also to release its apparatus and return it to normal.

When the called radio station has been selected and has sent out its return signal, and the calling radio station has responded 15 to this signal, the response causes the calling radio station to send out a series of groups of impulses corresponding to the groups of impulses recorded upon the carrier wave receiving register switch, the tens 20 receiving register switch and the units receiving register switch at the calling radio station. These groups of impulses, which are sent out upon the signaling intermediate frequency of the common carrier wave, are 25 respectively recorded upon a carrier wave receiving register switch, a tens receiving register switch and a units receiving register switch at the called radio station. When the sending of the last group of impulses 30 at the calling radio station and its receipt and registration at the called radio station are completed, tuning control switches at the calling and called radio stations become simultaneously operative for 35 bringing the transmitting and receiving antennae systems at these stations into tune with the pair of communicating carrier wave frequencies that has been selected for use, the antennae systems at both stations at the 40 same time discontinuing and being made unresponsive to the calling carrier wave frequency. The tuning control switch at each station selects the pair of carrier waves that has been recorded upon the carrier wave receiving register switch of the associated station, the transmitting antenna system of the calling station and the receiving antenna system of the called station being tuned to 45 one wave frequency of the pair, and the transmitting antenna system of the called station and the receiving antenna system of the calling station being tuned to the other 50 frequency of the pair.

Immediately upon being tuned to the selected pair of communicating carrier waves 55 the calling radio station applies to its transmitting antenna system its wave of the pair with both intermediate frequencies; but the calling radio station first makes a test for 60 the guarding intermediate frequency of the communicating carrier wave applied at the called radio station. If for any reason the guarding intermediate frequency of the called station carrier wave is not received 65 at the calling station, a busy tone is applied

to the calling subscriber's line and the connection released when the calling subscriber hangs up; the release of the calling station apparatus also bringing about the release of the called station apparatus through the 70 withdrawal of the guarding intermediate frequency that is applied to the individual or communicating carrier wave of the calling station from the moment that the tuning control switch at the calling radio station 75 operates. If, however, the test made by the calling radio station indicates the presence of the called station carrier wave with its guarding intermediate frequency, the calling station acts to close the talking circuit 80 of the radio trunk.

In the meanwhile the radio trunk at the called station has been operating from the moment the receipt of the last group of selecting impulses was completed, to extend 85 the circuit of the called station radio trunk to the local line that is being called. This is accomplished by a tens transmitting register switch and a units transmitting register switch that send to a local trunk, to 90 which the radio trunk has become extended, impulses to cause the selective operation of a connecting switch associated with the local trunk. The tens and units transmitting register switches send impulses in accordance 95 with the impulses recorded upon the associated tens and units receiving register switches of the called radio station, thus operating the automatic connecting switch of the local trunk to extend the trunk to the 100 called subscriber's line, and closing the talking circuit of the radio trunk when the line has been selected to complete the conversational connection.

At the end of the conversation, the hanging up of the telephone receiver at the calling subscriber's station releases the apparatus of the calling radio trunk and restores it to normal; and the restoration to normal of the calling radio trunk withdraws the calling station communicating carrier wave of the pair with its two intermediate frequencies. This causes the release and return to normal 110 of the apparatus of the called station radio trunk. In returning to normal, the receiving antenna systems of both radio stations are again made responsive to the common or calling carrier wave with its intermediate frequencies; excepting that if the release of the connection occurs at a time when the common carrier wave is in use by some other radio station, the apparatus of the two released stations do not become responsive to the common carrier wave until after the radio station that is calling has completed its 115 calling operation and withdrawn that wave.

In detail the operation of the system is as follows:—Let it be assumed that the subscriber at station S desires to get into communication with another subscriber whose 120

station is at a remote exchange with which connection is had by means of radio. The subscriber at station S takes his telephone receiver from its hook, and the resultant 5 operation of the associated line switch 2 connects the circuit of the calling line with an idle trunk 3 extending to a selector switch 4. The means for effecting this operation is well known in the art, and need not be described in detail. The calling subscriber at 10 station S then proceeds to operate his calling dial 1 to produce the groups of impulses that control the operation of the automatic selecting switches. The first group of impulses may be employed, in a well known way, to cause the operation of the selector switch 4 to bring its wipers into engagement with the terminals of the branch RT' of an 15 idle radio trunk RT.

20 When the calling line is thus extended to the radio trunk, a circuit is closed through the subscriber's station apparatus and over the conductors of the calling line that brings about the energization of the line relay 6. 25 Relay 6 in operating closes a circuit that extends from battery through the winding of the slow-release relay 7, front contact and armature of relay 6, and right-hand back contact and armature of relay 8 to ground.

30 Relay 7 in operating opens at its upper back contact the circuit subsequently used to restore the register switches, closes at its upper front contact a circuit for rendering effective the controlling and sending apparatus of the radio trunk, closes at its middle front contact a test circuit for making the radio trunk test busy, and prepares at its lower front contact a circuit for transmitting impulses under the control of line relay 35 40 6. The test circuit for making the radio trunk test busy extends from battery through the winding of relay 5, inner left-hand back contact and armature of relay 9, outer left-hand back contact and armature of relay 8, and middle front contact and armature of relay 7 to ground. Relay 5 in operating, at 45 its outer left-hand front contact and armature, connects battery to the sleeve of spring jack terminal 14 associated with branch RT' of the radio trunk; and at its inner left-hand front contact and armature connects ground to the test contact of line switch terminal 13 50 of the branch RT' of the radio trunk. At the same time, relay 5 in operating opens at 55 its outer left-hand back contact the circuit over which relay 9 is adapted to be energized by the insertion of plug 15 into spring jack terminal 14 of the radio trunk; and at its inner left-hand back contact it opens the circuit 60 over which the relay 11 of the line switch 13 is adapted to be held operated when the radio trunk is seized by a call from a distant radio station. Relay 5 in operating also opens at its right-hand back contact and 65 armature the branch including conductors 17 and 18 and retardation coil 16 over which impulses for the operation of line switch 13 and its associated connector switch 41 are transmitted by the operation of relay 107 when a call is received from a distant radio 70 station.

It has been assumed that the first group of impulses determined by the operation of the dial 1 at the calling subscriber's station S has resulted in the seizure of the radio 75 trunk RT. Upon the first of the interruptions of the line circuit in connection with the second group of impulses that is now transmitted by the operation of the dial, line relay 6 releases its armature; and as 80 relay 7 is slow in releasing and holds its armatures closed during the short interruptions that constitute the impulses, a circuit is completed that extends from battery through the winding of the stepping magnet a of register switch A, winding of associated slow release relay 36, normal contact and wiper A^{-1} of register switch A, conductor 28, lower armature and front contact of relay 7, back contact and armature of 85 line relay 6, and right-hand back contact and armature of relay 8 to ground. The impulse thus produced causes the register switch A to take one step, thus breaking the initial energizing circuit by way of wiper A^{-1} ; but an alternate energizing path has 90 been closed at the left-hand front contact and armature of relay 36, and as the relay 36 is slow in releasing, this energizing path through the winding of relay 36 and the 95 winding of the magnet of switch A is maintained during the impulses of the group that are now being transmitted. The register switch A therefore takes one step for each of the impulses of the group, and at the end of 100 the group line relay 6 remains energized, thus holding open the pulsing circuit by way of the winding of relay 36 and the winding of the associated stepping magnet a of register switch A, thus permitting relay 36 105 to release. The advance of the switch wipers of the register switch A has caused the wiper A^{-3} to close a path extending by way of outer right-hand back contact and armature of relay 36, conductor 27, and 110 upper front contact and armature of relay 7 to ground, thus identifying the stationary contact of switch wiper A^{-3} that corresponds in position in its row to the number of impulses in the group that has just been transmitted.

The release of relay 36 at the end of the first group of impulses extends the pulsing conductor 28 by way of register switch wiper A^{-2} to the next register switch B of 115 the series, and the group of impulses determined by the next operation of the dial at calling station S causes the advance of the register switch B in the same manner as has been described in connection with 120 125 130

the operation of the first register switch A. The first impulse of this group operates and locks up the relay 38 associated with register switch B; and when switch B has advanced its wiper B³ to a point corresponding to the number of impulses in this particular group, the cessation of the impulses causes the release of relay 38, and the extension of the pulsing conductor 28 to the 10 next register switch C.

The succeeding group of impulses determined by the operation of the dial 1 at the calling subscriber's station S causes the advance of the wipers associated with register switch C in the same manner as described in connection with the operation of register switches A and B, the wipers being advanced to an extent corresponding to the number of impulses in this group, 15 and the relay 39 holding its armatures attracted during the receipt of the impulses, and releasing them at the end of the group.

The register switches A, B and C are thus set in accordance with the numbers 25 consecutively pulled upon the dial 1 at calling subscriber's station S. As the system is organized in this particular embodiment, the setting of the register switch A is in accordance with the particular radio station 30 that has associated with it the line of the subscriber who is being called, and the register switches B and C are set respectively in accordance with the tens and units digits of the called subscriber's line. If a 35 greater number of subscribers' lines are included in the group of lines associated with the radio station, then as many additional register switches such as B and C as are necessary may be included with their associated equipment to provide for the registration of the directory number of the called subscriber's line.

Concurrently with the registration upon the register switches A, B and C of the numbers pulled upon the calling subscriber's station dial, apparatus associated with the radio trunk has been operating to appropriate the common or calling carrier wave, if that wave is not at the time in use by some 40 other radio station, and to select and appropriate a pair of individual or communicating carrier waves for the subsequent use of the calling subscriber in establishing communicating relation with the called subscriber. When relay 7 operates at the moment the seizure of the radio trunk by the calling line is completed, it closes a circuit that extends from battery through the winding of relay 31, lower back contact and 45 armature of relay 40, conductor 26, lower back contact and armature of relay 10, and upper front contact and armature of relay 7 to ground. Relay 31 in operating closes a circuit that extends from battery through the winding of relay 33, inner right-hand 50

armature and back contact of relay 116, it being assumed that the common carrier wave is not in use by some other radio station, and right-hand front contact and armature of relay 31 to ground. If the common carrier 55 wave happens to be in use, relay 116 will be in its operated condition, as will subsequently be explained, and consequently the energization of relay 31 will not act to bring about the operation of relay 33 until the 60 common carrier wave is released by the other radio station that is using it. But assuming that the common carrier wave is not in use, the relay 33 is operated and acts to start the train of operations that results in a pair of 65 individual carrier waves being selected, and radio impulses sent out in accordance with the setting of the register switches to select the desired radio station and the desired subscriber's line at that station.

When the relay 33 operates, in the movement of its outer armature it shifts the conductors extending from the contacts of the signaling intermediate frequency relay 268 and guarding intermediate frequency relay 252 (Fig. 6), from their normal control over the radio signal receiving apparatus of the trunk, and gives them control over the radio signal transmitting apparatus of the trunk. In the movement of its middle armature the relay 33 closes a circuit that extends from battery through the right-hand armature and back contact of relay 199 (Fig. 5), winding of relay 200, then in parallel through the windings of relays 201, 191 and 181 of the radio transmitting system, conductor 272, left-hand armature and back contact of relay 114, conductor 34, normal contact and wiper P' of switch P and middle front contact and armature of relay 33 100 to ground. The closing of this circuit operates the relays 200, 201, 191 and 181. Relay 200 in operating starts the operation of the motor 146, and the associated generators 147 and 148 are driven to generate, respectively, 105 the plate current and the filament current for the energization of the radio transmitting system. Relay 200 in operating also closes at its lower front contact and armature a circuit by way of the outer right-hand back contact and armature of relay 114 for energizing relay 216, and that relay in operating connects the source of plate current 147 with the guarding intermediate frequency oscillator 168 to cause the oscillator 110 to apply this intermediate frequency to the carrier wave. At the same time the high frequency carrier wave is applied by the energization of the oscillator 171 upon the starting into operation of the plate current generator 147 and filament current generator 148. The operation of the relays 181, 191 and 201 acts to tune the input circuit of the modulator 180, the input circuit of the power amplifier 209, and transmitting 115 120 125 130

antenna TA to the frequency of the common carrier wave.

Before proceeding with a description of the further actions at the calling radio station, the effects upon the other radio stations of this application of the common carrier wave with its guarding intermediate frequency will be described. At each of the other radio stations that is not in use the radio receiving apparatus is normally in condition to respond to the common or calling carrier wave, the tuning branch by way of capacity 231 and back contact of relay 221 at each of said stations being closed, and the branches by way of capacities 232, 233, 234, 332, 333 and 334 and their associated controlling relay contacts being open. On account of the tuning due to the closure of the path by way of capacity 231 the common carrier wave energizes the radio receiving system at each such station, and the superposed guarding intermediate frequency is separated out by the frequency filter 235 and causes the energization of the associated detector 238, amplifier 245, and rectifier 251, the rectified current flowing through and energizing the guarding relay 252. The guarding relay at each of the non-busy stations in operating closes a circuit that extends from battery through the winding of relay 115, (Fig. 2), left-hand back contact and armature of relay 33, conductor 100, and front contact and armature of relay 252 to ground. At the radio stations that are in use, as calling stations, this circuit is kept open by the energization of relay 33 that results from the seizure of the radio trunk by the calling subscriber, as previously described; and at all radio stations that are using individual carrier waves for conversation, the receiving antenna system is tuned not to respond to the common or calling carrier wave.

Therefore, upon the seizure of the associated radio trunk by calling subscriber's station and the consequent application of the common carrier wave with its guarding frequency, the relays 115 at all of the radio stations that are not in use are immediately energized. When relay 115 operates it closes at its upper front contact and armature a circuit by way of the inner upper armature and back contact of relay 124' for operating relay 116; and relay 116 in operating locks up by way of its inner left-hand front contact and armature and the normally closed inner contact 120 of timer 118 to ground. Relay 116 in operating also breaks, at its inner right-hand back contact and armature, the path over which relay 31 brings about the operation of relay 33 when relay 31 is energized by the seizure of the associated radio trunk by a local calling line. Therefore the immediate effect of the transmission of the common carrier wave with its guard-

ing frequency by the calling radio station is to prevent any other radio station from operating its relay 33 to appropriate the common carrier wave and use it for initiating a call. Relay 116 in operating also opens a circuit 70 from ground by way of right-hand armature and back contact of relay 31, right-hand armature and back contact of relay 116, winding of relay 21 and conductor 93, the subsequent closure of which acts to restore 75 the associated receiving register and other switches that may in the meanwhile have been stepped from their normal positions.

Relay 116 also closes a circuit that extends from battery through the winding of relay 271 (Fig. 6), inner right-hand armature and back contact of relay 114, conductor 99, lower back contact and armature of relay 87, outer right-hand front contact and armature of relay 116, and right-hand back contact 80 and armature of relay 31 to ground. Relay 271 in operating as a result of the closure of this circuit disconnects from the coil 263 the signaling and talking intermediate frequency branch of the receiving antenna system, and connects it by way of coil 264 and rectifier 269 with the signal receiving relay 268. Thus each non-busy station is placed in a receptive condition with respect to the selecting impulses that are about to be transmitted 95 from the calling radio station.

When relay 115 at each of the non-busy radio stations operates, it closes a circuit that extends from battery through the winding of relay 105, inner lower front contact and armature of relay 115, outer upper armature and back contact of relay 124', and right-hand back contact and armature of relay 31 to ground. Relay 105 in operating locks up by way of its inner left-hand front contact 100 and armature and inner resting contact 104 of timer 101 to ground. Relay 105 in operating also closes a circuit that extends from battery through the winding of relay 5 (Fig. 1), inner left-hand armature and back contact 110 of relay 9, outer back contact and left-hand armature of relay 8, conductor 106, back contact and armature of relay 170, conductor 122, right-hand armature and back contact of relay 31, and inner right-hand front contact and armature of relay 105 to ground. Relay 5 in operating applies a busy test potential to the test terminals of line switch 13 and spring jack 14; and the grounding of the energizing circuit of relay 5 also produces a busy test condition on the selector switch terminal 4 of the trunk. Thus the non-busy radio trunk is safeguarded against seizure at any of its local terminals while any other radio station is calling. 115

Returning now to the operations that are taking place at the calling radio station, the relay 33 in attracting its armatures not only applies the common carrier wave and its superposed guarding intermediate frequency 120

as described, but also closes a circuit that extends from battery through the winding of relay 37, switch wiper P-⁶ and normal contact, switch wiper D-¹ and normal contact, 5 and middle front contact and armature of relay 33 to ground. Relay 37 in operating locks up by way of its inner right-hand front contact and armature, and inner contact 53 of timer 52 to ground. Relay 37 in operating 10 also closes a circuit that extends from battery through the winding of the stepping magnet d of switch D, the armature and back contact of this magnet, switch arm D-³ and its normal contact, and inner left-hand front 15 contact and armature of relay 37 to ground. The effect of the closure of this circuit is to cause switch D to take one step, the advance of the switch wipers to their second position breaking the energizing circuit of 20 the stepping magnet at switch arm D-³.

The above described movement of the switch arms of switch D closes a circuit that extends from battery through the winding of relay 271 (Fig. 6), inner right-hand armature and back contact of relay 114, conductor 99, inner lower armature and back contact of relay 60, off-normal contacts and switch arm D-¹ of switch D, normal contact and switch arm P-⁶, inner right-hand front 25 contact and armature of relay 37, and inner contact 53 of timer 52 to ground. The effect of the closure of this circuit is to operate relay 271; and this relay in operating disconnects the signalling and talking intermediate 30 frequency branch of the receiving antenna circuit from its normal connection with the talking circuit of the trunk, and connects it instead through the inductive coupling 264 to the rectifier 269 which modifies the received current for the operation of relay 268. 35

The movement of switch D to its first position from normal also closes a circuit that extends from battery through the winding of relay 220 (Fig. 5), winding of relay 221, 40 winding of relay 222, conductor 42, first contact from normal and associated switch arm D-³ of switch D, and inner left-hand front contact and armature of relay 37 to ground. As a result relays 220, 221 and 45 222 are all operated. Relay 220 in operating, closes branches to ground of the energizing circuits of the motor 146 and of relay 216, in parallel with the branches that are already closed in contacts of the relay 50 200. Relay 221 in operating opens the condenser branch 231 that normally tunes the receiving antenna circuit to the common carrier wave; and relay 222 in operating 55 closes the condenser branch 232 that tunes the receiving antenna system to one of the carrier wave frequencies of the first individual pair. Therefore, as a result of the first step taken by switch D on the operation of relay 37, the signalling intermediate 60 frequency relay 268 (Fig. 6) is brought into

operative relation with the receiving antenna system, and the receiving antenna system is tuned to the frequency of one of the waves of the first individual carrier wave pair. As will subsequently be described, 70 when any of the pairs of individual carrier wave frequencies is in use between two of the radio stations, each of the two stations transmits a different one of the high frequency waves of the pair with the signalling 75 or talking intermediate frequency constantly impressed upon it. Therefore, if the first pair of individual carrier waves is in use, when the receiving antenna system of the calling radio station is tuned to either one 80 of the frequencies of this pair, the superposed signalling or talking intermediate frequency is detected, amplified, and rectified, and causes the operation of relay 268. When relay 268 operates it closes a circuit that extends from battery through the winding of the stepping magnet d of switch D, armature and back contact of this magnet, outer resting contact 45 of timer 46, outer right-hand front contact and armature of relay 85 37, outer right-hand front contact and armature of relay 33, conductor 35, and front contact and armature of relay 268 to ground. The stepping magnet d attracts its armature, and in doing so opens the short circuit 90 that normally exists by way of the back contact of the stepping magnet armature around the high resistance winding of slow-release relay 47. Relay 47 then operates 95 and closes a circuit for the operation of relay 48 by way of front contact and armature of relay 47 and inner resting contact 49 of timer 46 to ground. Relay 48 in operating locks up by way of its inner left-hand front 100 contact and armature and timer contact 49 105 to ground; and also, at its outer left-hand front contact and armature, closes a circuit for the energization of the timer 46. Timer 46 consequently starts the slow inward movement of its plunger, and in doing so opens timer contact 45, which interrupts the energizing circuit of stepping magnet d; the circuit of the stepping magnet, however, having already been interrupted in effect 110 by the breaking of the short-circuit about the high resistance winding of relay 47. The associated switch arms are thus caused to take another step,—from their first to their second position from normal. In moving from its first to its second position, 115 switch arm D-³ breaks the energizing circuit that had previously existed for the operation of tuning relay 222 (Fig. 6), and closes, by way of conductor 43, an energizing circuit for the operation of tuning relay 120 223. As the energizing path for the operation of relays 220 and 221 is common to the branches through the various tuning relays, the relays 220 and 221 remain energized 125 when the branch through one of the tuning 120

relays is opened and that through another is closed.

The release of relay 222 and the operation of relay 223 changes the tuning of the receiving antenna system so that it becomes irresponsive to a frequency of the first individual carrier wave pair and becomes responsive to one of the second individual carrier wave pair frequencies. If the second pair of carrier waves is in use, the presence upon the carrier frequency of the superposed signaling and talking intermediate frequency causes the energization of relay 268.

When the timer 46 completes its inward movement, it opens its inner contact 49. This releases relay 48, which in turn de-energizes and permits the immediate return to normal of timer 46. When contacts 45 are closed upon the return to normal of the timer 46, if relay 268 has become energized as a result of the second pair of individual carrier waves being found to be in use, then a circuit is again completed for the energization of the stepping magnet *d* of switch D by way of the armature and back contact of the magnet, timer contact 45, outer right-hand front contact and armature of relay 37, outer right-hand front contact and armature of relay 33, conductor 35, and front contact and armature of relay 268 to ground. This causes another cycle of operations like those previously described in the course of which switch D advances its wipers to their third contact position from normal, and a test is made to determine the available or unavailable condition of the third pair of individual carrier waves. If this pair should also be found to be in use, and the relay 268 be consequently again energized, the switch D advances its wipers to their fourth contact position. As a result a circuit is completed that extends from battery through the winding of relay 40, fourth contact and wiper arm *D*⁻³ of switch D, and inner left-hand front contact and armature of relay 37 to ground. Relay 40 in operating locks up by way of its lower front contact and armature, conductor 26, lower back contact and armature of relay 10, and upper front contact and armature of relay 7 to ground. At the same time relay 40 in operating opens the talking circuit of the radio trunk, and applies a busy tone from the source 55 to that portion of the talking circuit extending back to the calling subscriber's station. Upon hearing this busy tone, the calling subscriber may replace his telephone receiver upon its hook, whereupon the connection is released and all apparatus restored to normal in a manner that will subsequently be described in connection with the release of a completed connection.

For the purpose of the present description it may be assumed that the first pair

of individual carrier wave frequencies is available for use. This being the case, when the switch D advances its wipers to their first contact position from normal and tunes the receiving antenna system to the answering one of the first pair of individual carrier waves, the signaling intermediate frequency relay 268 remains inert. Therefore, no circuit is closed by way of the contact of this relay for causing the switch D to take another step, and for causing the energization of the relay 47 and consequent energization of the relay 48. At the moment that the relay 37 was first energized, a circuit was closed extending from battery through the winding of relay 51, outer contact 50 of timer 52, outer left-hand armature and front contact of relay 37, and outer right-hand back contact and armature of relay 48 to ground. The operation of relay 51 closes the energizing circuit of the timer 52 and the timer starts the slow inward movement of its plunger, thus breaking contact 50 included in the initial energizing circuit of relay 51. But relay 51 remains energized by way of the locking circuit through its right-hand front contact and armature. As long as the energizing circuit of relay 51 remains closed the inward movement of the plunger of timer 52 continues; and if the relay 48 remains un-energized for a period of time determined by the setting of the timer 52, the timer completes its inward movement and opens its contacts 53, thus releasing relay 37. The interval of time required for the tuning of the receiving antenna system successively to each of the various individual carrier waves, and for the testing for the presence of these waves is less than that required for the timer 52 to complete the inward movement of its plunger; so that each pair of individual carrier waves that is tested and found in use causes the operation of relay 48 and the release of relay 51, and consequently of the timer 52, before the timer has moved its plunger far enough to open contact 53 and release relay 37.

Under the present assumption, that the first individual carrier wave is found available, timer 52 completes its movement and releases relay 37, and that relay in releasing opens the energizing circuit of the receiving antenna tuning branch of the wave frequency under test, thus re-establishing the normal tuning of the receiving system, and at the same time closes a circuit for starting the operation of the impulse mechanism 70 (Fig. 3). This circuit extends from battery through the winding of relay 68, outer contact 74 of timer 73, outer contact 71 of timer 79, normal contact and switch arm F⁻⁶ of switch F, off-normal contact and switch arm A⁻⁵ of switch A, inner right-hand back contact and armature of relay 36, con-

ductor 59, off-normal contact and switch arm D-2 of switch D, and inner left-hand back contact and armature of relay 37 to ground. The fact that this circuit includes a switch 5 arm A-5 of switch A and a back contact of the associated relay 36 prevents the release of the relay 37 from closing the circuit to the impulse apparatus 70 until the station register switch A has taken its registration 10 from the calling subscriber's dial. Assuming that this has occurred, the closure of the above-traced circuit operates relay 68 of the impulse apparatus 70, which relay locks up by way of its inner left-hand front contact and armature, and also closes at its outer right-hand front contact and armature a circuit for energizing the timer 73, this circuit being completed to the common operating ground by way of switch arm F-6 and 15 the path already traced. Timer 73 in operating opens at contact 74 the initial energizing path of relay 68, and at the end of the inward movement of its plunger closes at contact 75 a path to the common operating 20 ground for energizing relay 69. Relay 69 in operating closes at its right-hand front contact and armature a circuit to the common operating ground for energizing timer 79, and at the same time locks up to this 25 ground by way of its left-hand front contact and armature, inner contact 72 of timer 79, and outer contact 71 closed the instant timer 79 starts its inward movement. The 30 inward movement of timer 79 opens at contact 71 the locking circuit of relay 68; and that relay in releasing opens the energizing circuit of and releases timer 73. The inward movement of timer 79 continues until its plunger engages and opens inner contacts 72, 35 and the opening of these contacts releases relay 69, thus releasing and permitting the return of timer 79. The return of timer 79 to normal re-establishes the original circuit condition of the impulse apparatus 70, 40 whereupon the cycle of operation is again performed in the manner described and continues to be repeated as long as the operating ground is kept connected with the impulse apparatus circuit.

50 The operation of the impulse apparatus 70, as described, causes a series of slowly recurring energizations and deenergizations of the relay 68, which have the effect of causing the application of a series of signaling intermediate frequency impulses to the carrier wave that is being sent out from the calling radio station, and of causing a step by step advance of a series of switches E, F, G, H, K, L, M and N that co-operate with 55 the register switches A, D, B and C in determining the number of radio impulses in each group sent out. Upon the first energization of the relay 68 of the impulse apparatus 70, a circuit is completed that extends from battery through the stepping 60 magnet e of switch E, inner right-hand back contact and armature of relay 76, outer right-hand back contact and armature of relay 179, inner right-hand front contact and armature of relay 68, and thence to ground by way of the previously-traced path closed upon the release of relay 37. This energizes the stepping magnet of switch E; but the advance of the switch arms does not occur until the energizing circuit of the stepping magnet is broken. The first energization 65 of relay 68 of the impulse apparatus also closes a circuit that extends from battery through the winding of relay 67, outer right-hand armature and back contact of relay 76, inner left-hand back contact and armature of relay 179, and outer left-hand front contact and armature of relay 68 to the common ground closed upon the release of relay 37. The effect of the energization 70 of relay 67 by the closure of the above circuit is to prevent the closure of a circuit for energizing relay 215 (Fig. 5) which otherwise would be closed immediately upon the release of relay 37. The energizing circuit 75 for relay 215, which relay controls the application of the signaling intermediate frequency to the carrier wave, extends from battery through the left-hand winding of relay 215, conductor 66, lower back contact and armature of relay 60, conductor 65, back contact and armature of relay 67, switch arm F-7 and its normal contact, off-normal contacts and switch arm A-5, inner right-hand back contact and armature of relay 36, conductor 59, off-normal contacts and switch arm D-2, and inner left-hand back contact and armature of relay 37 to ground. This 80 energizing circuit is closed at one point by the release of relay 37 upon the selection of 85 the individual carrier wave; but at practically the same instant it is opened at another point by the operation of relay 67 that occurs at the moment relay 68 of the impulse 90 apparatus 70 operates.

When relay 68 releases at the end of the first half cycle of operation of the impulse apparatus 70, the energizing circuits of both the stepping magnet of switch E and of relay 67 are opened. The release of the 95 stepping magnet causes the switch arms of switch E to take one step, to their first position from normal, and the release of relay 67 closes the energizing circuit of relay 215, traced above, and causes that relay to apply 100 the signaling intermediate frequency to the carrier wave. The application of the signaling intermediate frequency continues until relay 68 of the impulse apparatus again 105 operates, when relay 67 is energized to break the energizing circuit and release relay 215, and the stepping magnet of switch E is again energized to prepare for the taking 110 of the next step by the switch. This action continues until the switch arms of switch E 115

120

125

130

135

are moved to the point where arm E^{-2} engages a contact point connected with and corresponding in number to the contact point upon which switch arm A^{-3} of switch 5 A is resting, each retraction of the armatures of relay 68 causing an additional step of switch E and an additional application of the signaling intermediate frequency to the carrier wave. When switch arm E^{-2} is 10 moved, upon the release of relay 68, to the contact point identified by the switch arm A^{-3} , a circuit is closed that extends from battery through the winding of relay 76, switch arm E^{-2} , switch arm A^{-3} , outer right-hand back contact and armature of relay 36, conductor 27, and upper front contact and armature of relay 7 to ground. When 15 relay 76 operates it locks up to the holding conductor 27 by way of its inner left-hand front contact and armature. At its outer left-hand front contact and armature relay 76 closes a circuit for the energization of relay 153 including switch arm F^{-1} and its normal contact, and to ground by 20 way of the inner right-hand front contact and armature of relay 33.

Relay 76 at its inner right-hand armature disconnects the impulse conductor controlled by the inner right-hand armature of 25 relay 68 from the stepping magnet of switch E and connects it by way of switch arm F^{-2} and its normal contact to the stepping magnet of switch F. At its outer right-hand armature relay 76 disconnects the winding 30 of relay 67 from the impulse circuit controlled at the outer left-hand armature of relay 68 and connects it to switch arm F^{-4} through which, at a later stage in the operation, the relay 67 is again brought under the 35 control of the outer left-hand armature of relay 68.

The release of relay 67 at this time again 40 closes the energizing circuit of relay 215 (Fig. 5), so that the signaling intermediate frequency is again applied to the common carrier wave. The impulse apparatus 70 continues to operate, and when relay 68 again attracts its armatures the stepping magnet f of switch F is energized. Upon 45 the subsequent release of relay 68 the stepping magnet is released and causes switch F to take one step and move its switch arms to their first contact points from normal. The result of this step taken by switch F is 50 that switch arm F^{-6} opens the energizing circuit of the impulse apparatus 70 and stops the operation of the interrupting devices; switch arm F^{-7} opens the energizing circuit of relay 215 and withdraws the signaling intermediate frequency from the common carrier wave; and switch arm F^{-1} , as it moves to 55 its first contact point from normal, closes a circuit that extends from battery through the winding of relay 60 (Fig. 2), conductor 121, front contact and armature of slow-re-

lease relay 153, first contact point from normal and switch arm F^{-1} , outer left-hand front contact and armature of relay 76, conductor 58, and inner right-hand front contact and armature of relay 33 to ground. 70

Relay 60 is operated during the interval this circuit remains closed before relay 153 releases, and closes a locking circuit for itself by way of armature and back contact of relay 61, upper front contact and armature of relay 60, and inner right-hand front contact and armature of relay 33 to ground. Relay 60 also closes a circuit that extends from battery through the winding of relay 271 (Fig. 6), inner right-hand armature and 80 back contact of relay 114, conductor 99, inner lower armature and front contact of relay 60, and inner right-hand front contact and armature of relay 33 to ground. Relay 271 in operating disconnects the signaling 85 and talking intermediate frequency branch of the receiving antenna system from coil 263 and connects it with coil 264 and rectifier 269, thus placing relay 268 in condition to respond to received signals. 90

At the same time relay 60 at its outer lower armature and back contact introduces another break into the energizing circuit of the signaling frequency controlling relay 215. The ground applied by way of the upper front contact and armature of relay 60 also completes a circuit by way of the right-hand armature and back contact of relay 57 for energizing the timer 62.

The movement of switch F to its first position from normal, which has stopped the operation of the impulse apparatus 70 and has caused the operation of relay 60, as described, also places relay 57 (Fig. 2) under the control of the signaling intermediate frequency receiving relay 268 (Fig. 6). This circuit extends from battery through the winding of relay 57, conductor 56, switch arm F^{-3} , and its first contact from normal, conductor 54, outer right-hand back contact 110 and armature of relay 37, outer right-hand front contact and armature of relay 33, conductor 35, and front contact and armature of relay 268 to ground. The condition, therefore, which now exists is that the impulse apparatus 70 is at rest, the signaling intermediate frequency is withdrawn from the common or calling carrier wave, which wave is still being sent out with its guarding intermediate frequency superposed upon it, the relay 268 is connected with the receiving antenna system to respond to any signaling intermediate frequency impulse that may be received, and, in responding, to operate relay 57, and the plunger of timer 62 is traveling 115 inwardly to close the associated contact 63 at the end of the interval for which the timer is set. If the timer 62 is permitted to complete the inward movement of its plunger and close contact 63, a circuit is closed that 120

125 130

extends from battery through the winding of relay 40, and timer contact 63 to ground. The closure of this circuit interrupts the talking conductor of the radio trunk, connects the source of busy tone current 55 with the calling subscriber's line, and breaks the energizing circuit of relay 31, thus releasing that relay and the relay 33 which it controls and causing the withdrawal of the common carrier wave. Then when the calling subscriber hangs up in response to the busy tone, the connection is released in a manner which will be more fully described hereinafter. In order that the succeeding stages of the establishment of the connection may be proceeded with it is necessary that an impulse for energizing relay 268 and causing it to energize relay 57 shall be received before the timer 62 closes the contacts 63. The manner in which this impulse is sent out by the called radio station, in case that station is available for use and responds to the station selecting impulses controlled by switch F, will now be described.

As has already been described, the application by the calling radio station of the common carrier wave with its guarding frequency, has caused the operation of the relays 252, 115, 116 and 105 of all the non-busy radio stations. Therefore, at each of these stations a circuit is completed that extends from battery through the winding of relay 271, inner right-hand armature and back contact of relay 114, conductor 99, lower back contact and armature of relay 87, outer right-hand front contact and armature of relay 116, and to ground by way of the right-hand back contact and armature of relay 31. The relay 271 at each of the non-busy radio stations is thus energized to bring relay 268 into operative relation with the signaling or talking intermediate frequency branch of the receiving antenna circuit. When the release of relay 37 (Fig. 2) at the calling radio station starts the impulse apparatus 70 and energizes relay 215 (Fig. 5) to apply the signaling intermediate frequency to the calling carrier wave, the relay 268 (Fig. 6) at each of the non-busy radio stations is energized and closes a circuit that extends from battery through the winding of relay 32 (Fig. 2), outer right-hand back contact and armature of relay 33, conductor 35, and front contact and armature of relay 268 to ground. When relay 32 operates it closes a circuit that extends from battery through the left-hand winding of relay 172 (Fig. 4), conductor 109, and front contact and armature of relay 32, and thence to ground by way of outer lower armature and back contact of relay 124' and inner contact 126 of timer 127. Relay 172 in operating locks up by way of its right-hand winding, right-hand front contact and armature, conductor 122, left-hand armature and back con-

tact of relay 31, and inner right-hand front contact and armature of relay 105 to ground.

As previously described, each step taken by the switch E at the calling radio station in its movement toward the identified contact of the station register switch A is accompanied by an application of the signaling intermediate frequency to the common carrier wave; and each application of the signaling frequency causes all of the relays 32 at the various non-busy radio stations to attract their armatures. When the relay 32 at each station releases its armature it closes a circuit that extends from battery through the stepping magnet *ar* of the station selecting switch AR, right-hand winding of relay 123, left-hand front contact and armature of relay 172, normal contact and switch arm AR^{-1} , conductor 108, outer right-hand armature and front contact of relay 105, and back contact and armature of relay 32 to ground by way of relay 124' and contact 26. This energizes the stepping magnet *ar* and operates relay 123, which locks up by way of its left-hand winding and its inner left-hand front contact and armature to the inner contact 126 of timer 127. At the same time relay 123 closes at its right-hand front contact and armature a short circuit of the energizing path initially completed by way of switch arm AR^{-1} and its normal contact, so that the stepping magnet *ar* remains under the control of relay 32 after the switch AR has moved from normal.

Upon the first retraction of the armature of relay 32, as described, a circuit is completed that extends from battery through the winding of relay 124, outer timer contact 125, outer left-hand armature and front contact of relay 123, inner right-hand front contact and armature of relay 123, outer right-hand armature and front contact of relay 105, and back contact and armature of relay 32 to ground over the path previously traced. Relay 124 locks up to this energizing circuit at its right-hand front contact and armature and at the same time at its left-hand front contact and armature closes the energizing circuit of the timer 127. The timer thereupon starts the inward movement of its plunger, which continues until the energizing circuit of relay 124 is broken by the subsequent operation of the relay 32.

The period of operation of timer 127 is so adjusted that the normal impulse interval from the retraction of the armature of relay 32 to its subsequent attraction is less than the interval required for the timer to complete its inward movement and open its contact 126. Therefore, the relay 123 is held energized by way of timer contacts 126 during the sending of the station selecting im-

pulses, and the energizing circuit by way of the right-hand armature and front contact of relay 123 remains closed for the control of the stepping magnet of switch AR by relay 32. At the end of the station selecting impulses (marked by the movement of switch F at the calling radio station to its first position from normal), relay 32 is de-energized and continues deenergized to hold relay 124 operated long enough to permit timer 127 to complete the inward movement of its plunger. At the end of the inward movement the plunger opens its inner contact 126, thus opening the energizing circuits of both windings of relay 123 and of the stepping magnet of switch AR. As a result the release of the stepping magnet causes switch AR to take its final step to advance its switch arms to a contact point corresponding to the contact point to which the arms of the transmitting register switch E at the sending station have been advanced, and therefore also corresponding to the point to which the arms of the receiving register switch A has been advanced by the calling subscriber's dial impulses. At the same time the release of relay 123 disconnects at its outer right-hand contacts the winding of relay 128 from its direct energizing path to conductor 122, and connects it to the switch arm AR⁻⁴. If the number of station selecting impulses transmitted has been such as to advance switch arm AR⁻⁴ to the particular contact point connected to the left-hand front contact of relay 128, that relay remains locked up by way of the holding path through the winding of relay 170 to conductor 122. If the station selecting impulses received have been either less or more in number than the number required to move switch arm AR⁻⁴ to this particular contact, then relay 128 is released upon the release of relay 123. The left-hand front contact of relay 128 is wired to a different contact point of switch arm AR⁻⁴ at each of the radio stations, so that for any given number of station selecting impulses the relay 128 at only one of the radio stations is maintained energized, the relays 128 at all of the other stations being released.

Assuming first that the particular station illustrated is not the one that is being called for, and that relay 128 is therefore released at the end of the station selecting impulses, the release of the relay prepares a circuit that extends from battery through the winding of the stepping magnet *or* of switch AR, armature and back contact of that magnet, off-normal contacts and switch arm AR⁻³, inner right-hand back contact and armature of relay 128, conductor 92, normal contact and switch arm P⁻¹, conductor 93, winding of relay 21, outer right-hand back contact and armature of relay 116, and right-hand back

contact and armature of relay 31 to ground. The above circuit is not completed at this time, for the reason that relay 116 is held energized until relay 115 is released by the de-energization of the guarding intermediate frequency relay 252 (Fig. 6). In this way the switches AR and associated switches of the various non-busy stations that are not wanted are kept unresponsive to the subsequent impulses sent out from the calling radio station, and are not again made responsive until the release of relay 252 marks the termination of the calling operation and the release of the common carrier wave. When relay 116 is finally released, the circuit traced above in detail energizes the stepping magnets of all of the switches AR at the various radio stations that were not being called, and returns these switches to normal, at which time the energizing circuit is opened at switch arm AR⁻³.

We will now assume that the particular radio station illustrated is the one that is being called, and that therefore, relay 128 has become locked up over the holding path by way of left-hand front contact and armature of relay 128, winding of relay 170, conductor 122, left-hand armature and back contact of relay 31, and inner right-hand front contact and armature of relay 105 to ground. The inclusion of the winding of relay 170 in this holding path causes relay 170 to operate and break the energizing circuit by way of its back contact through the winding of relay 5 (Fig. 1), thus releasing relay 5 and withdrawing the busy condition at the terminals of the trunk heretofore maintained. But at the same time relay 170 closes at its front contact a circuit that extends from battery through the winding of relay 107 (Fig. 2), conductor 110, right-hand back contact and armature of relay 140, front contact and armature of relay 170, and thence to ground over the path previously traced. Relay 107 in operating closes the bridge of branch RT² of the associated radio trunk that extends by way of conductors 17 and 18, retardation coil 16, and resting contacts of relays 9 and 5. The effect of the closure of this bridge by relay 107 is to energize first relay 12 and then relay 11 of the line switch 13 upon which the branch RT² terminates; the result of the energization of relays 11 and 12 being to cause the line switch 13 to seize an idle trunk extending to a connector switch 41 in a manner well known in the art, to clear the talking conductors of branch RT² of their normal connection by way of relays 12 and 11 to battery and to ground, and to operate relay 8. Relay 8 in operating opens at its right-hand armature and back contact the impulse transmitting path normally under control of line relay 6, and closes at its right-hand armature and front contact a path for the energization of

relay 10. Relay 10 in operating disconnects the talking conductors of the radio trunk from their normal branch RT' and connects them with their alternate branch RT² extending to the line switch 13. When relay 8 operates it also breaks at its left-hand armatures and their back contacts the normal paths extending from the test contact of selector switch 4 to the winding of relay 5, 10 and from the test contact of spring-jack terminal 14 to the winding of relay 9, and connects these test contacts to ground and battery, respectively, to produce a busy test condition on the test terminals of selector 15 switch 4 and spring-jack 14.

In addition to causing the extension of the selected radio trunk by way of its line switch 13 to a local trunk and connector switch 41 as described above, the maintained 20 energization of relay 128 and release of relay 123 at the end of the station selecting impulses closes a circuit that extends from battery through the winding of relay 179 (Fig. 3), conductor 142, normal contact and 25 switch arm Y⁻², off-normal contacts and switch arm AR⁻², outer right-hand front contact and armature of relay 128, inner right-hand back contact and armature of relay 123, conductor 108, outer right-hand 30 armature and front contact of relay 105, back contact and armature of relay 32, outer lower armature and back contact of relay 124', conductor 64, and normally closed inner contact 126 of timer 127 to ground. The 35 closure of this circuit energizes relay 179, which then operates to start the impulse apparatus 70 and to apply the common carrier wave with its signaling intermediate frequency for a period determined by the 40 operation of the switch Y (Fig. 4). When relay 179 operates it closes a circuit from battery through the winding of relay 114 (Fig. 5), conductor 143, and inner right-hand front contact and armature of relay 45 179 to ground. Relay 114 in operating connects with the grounded conductor 143, the windings of the tuning relays 181, 191 and 201 for tuning the transmitting antenna system of the called station to the frequency 50 of the common carrier wave, and also the winding of common relay 200 for starting the operation of the plate and filament current generators to generate and apply the common carrier wave. But the guarding 55 intermediate frequency is not applied, as the break in its energizing circuit at the outer right-hand back contact and armature of relay 114 prevents the operation of relay 216. At the same time relay 114 opens the 60 circuit of the rectifier-controlling relay 271 (Fig. 6) so that the signaling intermediate frequency relay 268 will not be energized to operate relay 32 during the sending out of the signaling intermediate frequency from 65 the called radio station. Relay 114 also

opens conductor 34 to avoid applying a ground that would energize the circuits controlled by relay 33 that are used in calling.

Relay 215 is energized to apply the signaling intermediate frequency to the common carrier wave at the called station by means of a circuit that extends from battery through the left-hand winding of relay 215, conductor 66, outer lower back contact and armature of relay 60, conductor 65, back contact and armature of relay 67, switch arm F⁻⁷ and normal contact, switch arm F⁻⁶ and normal contact, outer left-hand armature and front contact of relay 179, 70 conductor 145, contacts and switch arm Y⁻¹ and off-normal contacts and switch arm AR⁻⁵ to ground. A branch from battery through the energizing network of the impulse apparatus 70 is closed to this same 75 ground by way of the outer left-hand armature and front contact of relay 179 when that relay operates. The closure of this energizing circuit of the impulse apparatus 70 causes the intermittent closing and opening of a circuit that extends from battery through the stepping magnet y of switch Y (Fig. 4), conductor 144, outer right-hand front contact and armature of relay 179, 80 inner right-hand front contact and armature of relay 68, and thence to the previously traced ground by way of outer left-hand armature and front contact of relay 179 and conductor 145. At each opening of this energizing circuit the switch Y takes one 85 step, and after an interval of time which could be measured by any desired number of steps of the switch but which in the present instance, is arbitrarily chosen as the time consumed by the taking of four steps, 90 switch Y moves its arms to the point where arm Y⁻² breaks the energizing circuit of relay 179. Relay 179 in releasing withdraws the common carrier wave with its signaling 95 intermediate frequency and opens the stepping circuit of the switch Y. The movement of the arms of switch Y to their fourth contact position from normal prepares paths for the control of the individual carrier wave selecting and local station selecting impulses by the radio impulses now 100 about to be sent out by the calling radio station.

The effect at the calling radio station of the above described sending out of the common or calling carrier wave with its applied intermediate signaling frequency by the selected radio station will now be considered. As was previously described, the switch F at the calling radio station is at 120 this time standing in its first contact position from normal, the impulse apparatus 70 is at rest, the plunger of the timer 62 is moving inwardly to apply the busy tone 125 at the end of the interval that it measures, 130

and the signal receiving relay 268 and its controlled relay 57 are awaiting the receipt of the return signal from the called radio station that is, the common or calling carrier wave modulated by the signaling intermediate frequency wave. When this signal is received, which in the normal operation of the system is while the plunger of timer 62 is still some distance from the inward limit of its movement, relay 268 operates and closes a circuit that extends from battery through the winding of relay 57 (Fig. 2), conductor 56, switch arm F⁻³ and its first contact, conductor 54, outer right-hand back contact and armature of relay 37, outer right-hand front contact and armature of relay 33, conductor 35, and front contact and armature of relay 268 to ground. Relay 57 in operating opens at its right-hand armature and back contact the energizing circuit of the timer 62, thus stopping the inward movement of the plunger and restoring the timer to normal. At its right-hand armature and front contact relay 57 applies the ground by way of upper front contact and armature of relay 60 to complete the energizing circuit of relay 61, and this relay thereupon operates to break the locking circuit of relay 60 that has been maintained by way of its upper front contact and armature.

When relay 60 releases it opens at its inner lower front contact and armature the energizing circuit of relay 271 (Fig. 6), thus disconnecting the rectifier 269 and the signal receiving relay 268 and restoring to its normal condition this branch of the receiving antenna circuit. At its upper armature and back contact relay 60 in releasing applies ground by way of conductor 78, switch arm F⁻² and the first, second and third associated contacts, and outer left-hand back contact and armature of relay 179 to the energizing conductors of the impulse apparatus 70. The impulse apparatus thereupon causes relay 68 again to commence the slow making and breaking of its contacts, thus causing the operation of the stepping magnet of switch F over a circuit that extends from battery through the winding of the magnet f, first, second and third contacts and switch arm F⁻⁵, inner right-hand front contact and armature of relay 76, outer right-hand back contact and armature of relay 179, and inner right-hand front contact and armature of relay 68 to the operating ground which is now applied by way of outer left-hand armature and back contact of relay 179, first, second and third contacts and switch arm F⁻², conductor 78, upper back contact and armature of relay 60, and inner right-hand front contact and armature of relay 33 to ground. Switch F therefore continues to step until it moves its switch arms to their fourth contact posi-

tion, at which time the energizing circuit of the impulse mechanism 70 is broken at switch arm F⁻², the energizing circuit of the stepping magnet of switch F is broken at switch arm F⁻⁵, and an energizing circuit is completed for the signaling frequency applying relay 215 by way of conductor 66, lower back contact and armature of relay 60, conductor 65, back contact and armature of relay 67, switch arm F⁻⁷ and its fourth contact point, conductor 79, fourth contact point and switch arm F⁻², conductor 78, upper back contact and armature of relay 60, and inner right-hand front contact and armature of relay 33 to ground. As a result of the closure of this circuit the signaling intermediate frequency is again applied to the common carrier wave.

In the meanwhile the switch Y at the called radio station has been advancing under the control of the associated impulse apparatus 70 at that station, as has been described; and shortly before the switch F at the calling radio station reaches its fourth position and effects the circuit changes described above, the switch Y at the called radio station reaches and comes to rest in its fourth position, and in so doing prepares the circuits at the called radio station for the receipt of the carrier wave selecting impulses and the local line selecting impulses that are now about to be sent out from the calling radio station.

At the calling radio station the arrival of the switch F at its fourth contact position extends a ground for the purpose of energizing the impulse apparatus 70 by way of inner right-hand armature and front contact of relay 33, upper armature and back contact of relay 60, conductor 78, switch arm F⁻² and its fourth contact, conductor 79, inner right-hand armature and back contact of relay 39 (associated with the units receiving register switch C), switch arm C⁻⁵ and its off-normal contacts, switch arm N⁻⁸ and associated contacts; outer left-hand back contact and armature of relay 179 to the energizing conductors of impulse apparatus 70.

At the same time the movements of switch arms F⁻⁴ and F⁻⁵ to their fourth contact positions place signaling frequency control relay 67 and stepping magnet g of the carrier wave transmitting register switch G under the control of the impulse apparatus 70. The energizing circuit of the relay 67 extends from battery through the winding of that relay, outer right-hand armature and front contact of relay 76, switch arm F⁻⁴ and its fourth contact point, outer right-hand armature and back contact of relay 85, inner left-hand back contact and armature of relay 179, and outer left-hand front contact and armature of the impulse relay 68 to the same path to ground over which the

energizing circuit of the impulse apparatus is closed. The energizing circuit of the stepping magnet g of switch G extends from battery through the winding of the 5 magnet, inner right-hand back contact and armature of relay 85, fourth contact point and switch arm F^{-5} , inner right-hand front contact and armature of relay 76, outer right-hand back contact and armature of 10 relay 179, and inner right-hand front contact and armature of impulse relay 68 to the energizing ground of the impulse apparatus. Each time the relay 68 is energized the stepping magnet of the switch G 15 is energized to prepare for the advance of the switch, and relay 67 is energized to break the energizing circuit of relay 215 and withdraw the signaling intermediate frequency from the common carrier wave. 20 Then, upon the deenergization of the impulse relay 68, the stepping magnet is released to advance switch G one step, and at the same time relay 67 is released to close the energizing circuit of relay 215 and 25 cause the reapplication of the signaling intermediate frequency. Switch G is thus advanced step by step with an accompanying application of a corresponding number of signaling impulses to the common carrier 30 wave, until the switch arm G^{-1} engages a contact corresponding with the contact upon which switch arm D^{-6} of the carrier wave receiving register switch D is resting. When this occurs a circuit is closed that 35 extends from battery through the winding of relay 85, switch arms G^{-1} and D^{-6} with their corresponding contacts, and inner left-hand back contact and armature of relay 37 to ground. Relay 85 in operating locks up 40 to the holding conductor 27 by way of its left-hand front contact and armature. At its inner right-hand armature relay 85 shifts one of the impulse conductors from the winding of stepping magnet of switch 45 G to the winding of the stepping magnet h of change-over switch H by way of arm H^{-1} of that switch, and at its outer right-hand armature relay 85 disconnects the energizing winding of relay 67 from the other impulse conductor and extends it to switch 50 arm H^{-2} to be subsequently closed to the impulse conductor after switch H has been moved two steps.

The switch D, it will be remembered, is 55 the switch that registers the pair of individual or communicating carrier waves that has been found available for use; and the switch G by the signalling impulses which it causes to be sent out, identifies the particular pair 60 of individual carrier waves that has been registered by switch D, and causes a register switch at the selected radio station to register this same pair of individual carrier waves for subsequent use when the connection is 65 established. Turning now to the operation

that is taking place at the called radio station, it has previously been shown how switch Y comes to rest in its fourth position from normal shortly before the switch F at the calling station reaches its fourth position 70 and starts the sending of the impulses controlled by switch G. Therefore when the first signal impulse is sent out from the calling station, during the interrupter half cycle between the movement of the arms of switch F to their fourth contact positions and the ensuing operation of relay 68 that causes relay 67 to operate and break the signal applying circuit, the relay 268 at the called station responds to this impulse and operates 75 relay 32; and relay 32 in operating closes a circuit that extends from battery through the left-hand winding of relay 173 (Fig. 4), fourth contact and switch arm Y^{-3} , conductor 109, and front contact and armature of 80 relay 32 to ground at timer contact 126. Relay 173 operates and locks up by way of its right-hand winding and right-hand front contact and armature, conductor 122, left-hand armature and back contact of relay 31, 85 and inner right-hand front contact and armature of relay 105 to ground. Relay 173 in operating also prepares for subsequent closure of the energizing circuit by means of 90 which the relay 32 transmits impulses in accordance with the radio impulses received, for the operation of the receiving register switches, V, BR, and CR. This circuit, which is completed when relay 32 releases at 95 the end of each radio impulse, extends from battery through the stepping magnet v of switch V, left-hand winding of relay 129, normal contact and switch arm V^{-1} , left-hand armature and front contact of relay 173, 100 fourth contact and switch arm Y^{-2} , off-normal contacts and switch arm AR^{-2} , outer right-hand front contact and armature of relay 128, inner right-hand back contact and armature of relay 123, conductor 108, outer 105 right-hand armature and front contact of relay 105, back contact and armature of relay 32, outer lower armature and back contact of relay 124', and inner contacts 126 of timer 127 to ground. Relay 129 in operating 110 closes at its inner left-hand armature and front contact a short circuit of the initial energizing branch of the impulse circuit by way of switch V^{-1} . At its inner right-hand front contact and armature, relay 129 closes 115 a locking circuit that includes its right-hand winding and extends to ground by way of inner contacts 126 of timer 127. Relay 129 in operating also closes a circuit that extends from battery through the winding of relay 124, outer normally closed contacts 125 of timer 127, outer right-hand front contact and armature of relay 129, conductor 109, front contact and armature of relay 32, and thence to ground by way of resting contact 120 of relay 124' and timer contacts 126. When 125 125 established. Turning now to the operation

relay 124 operates as a result of the closure of this circuit, it closes the energizing circuit of timer 127 and starts the inward movement of the plunger. If this movement continues uninterrupted until the inner contacts 126 are opened, the locking circuit of relay 129 will be opened and that relay released. But the movement of the armature of relay 32 in response to the radio impulses is such that as long as the impulses are being received relay 32 does not hold its front contact closed long enough to permit the full inward movement of the plunger of the timer 127. Upon each retraction and following attraction of the armature of relay 32 that accompanies each intermission of the signalling intermediate frequency at the calling station, the stepping magnet v of switch V is energized over the circuit previously traced and is then deenergized to cause the switch to take one step. When the switch G at the calling radio station finds the contact identified by switch D at that station and comes to rest, the steady application of the signalling intermediate frequency at the calling station during the time required for the change-over switch H to effect its advance causes a steady energization of the relay 32 at the called radio station; and this steady energization of relay 32 holds closed the energizing circuit of relay 124 associated with the timer 127 long enough to permit the full inward movement of plunger of timer 127 and the breaking of contacts 126. This breaks the locking circuit by way of the right-hand winding of relay 129; and relay 129 in releasing shifts the stepping or impulse circuit from the stepping magnet of switch V to the stepping magnet of switch BR, and, by way of its outer left-hand armature and front contact, applies ground to switch arm V^{-1} to identify the contact upon which it is resting: The stepping or impulse circuit is shifted to the next receiving register switch in the series by way of the inner left-hand armature and back contact of relay 129, switch arm V^{-2} and its off-normal contacts, switch arm BR^{-1} and its normal contact, left-hand winding of relay 130, and winding of stepping magnet br of switch BR to battery. The circuit is thus extended to place the next receiving register switch in the series under control of the signal receiving relays 268 and 32.

In the stage of the operation just described, the pair of individual or communicating carrier waves to be used, as registered on switch D at the calling radio station, is registered upon switch V at the called station through the medium of switch G at the calling station. In the stages of operation that are now to be described, the tens digit and units digit of the called subscriber's line number which are registered upon re-

ceiving register switches B and C at the calling radio station are to be registered upon receiving register switches BR and CR of the called radio station through the medium of the transmitting register switches K and M at the calling station. 70

The operation of transmitting the registration of switches B and C to switches BR and CR at the called radio station is substantially the same as the operation that has been described for transmitting the registration of the carrier wave registering switch D to the corresponding register switch V at the called station. After the carrier wave transmitting register switch G 75 has found the identified contact of the carrier wave receiving register switch D and the relay 85 has operated, the energizing circuit of the relay 67 is opened at switch arm H^{-2} until the change-over switch H has taken 80 two steps. While the energizing circuit of relay 67 is open the signalling intermediate frequency is applied steadily, and the relay 32 at the called radio station is held energized to effect the release of relay 129 and the transfer of the stepping circuit to relay 130 and its associated tens receiving register switch BR, as has been described. When the switch H at the calling radio station has taken two steps, the impulse circuit from the impulse apparatus 70 is extended by way of switch arm H^{-1} and its second contact point, and the inner right-hand armature and back contact of relay 80 to stepping magnet k of the tens transmitting register switch K. At 85 the same time the energizing circuit of relay 67 is placed under the control of one of the impulse conductors of apparatus 70 by way of the switch arm H^{-2} and its second contact point and the outer right-hand armature 90 and back contact of relay 80. 95

The switch K is now advanced step-by-step; and each step is accompanied by an application and withdrawal of the signalling intermediate frequency so that the switch BR at the called radio station is correspondingly advanced step-by-step under the control of the signal receiving relay 268 and the associated relay 32. When the switch K reaches the contact point identified by the switch arm B^{-3} of the tens receiving register switch B, relay 80 is operated, locks up to the holding conductor 27, and shifts the impulse circuit from stepping magnet k of switch K to stepping magnet l of the associated change-over switch L. The operation of relay 80 also extends the energizing circuit of relay 67 to the switch arm L^{-3} , where it remains open until the switch L has taken two steps. Therefore 100 105 110 115 120 125 130 the energizing circuit of relay 215 (Fig. 5) remains closed during this interval and the signalling intermediate frequency is steadily applied to the common carrier wave. The effect of this at the called radio station is

again steadily to hold relay 32 energized for a relatively long interval, during which interval the relay 124 associated with timer 127 is held steadily energized by way of 5 outer right-hand front contact and armature of relay 130, conductor 109, and to ground by way of front contact and armature of relay 32. This causes timer 127 to open its inner contacts 126, thus releasing relay 130 10 and effecting the transfer of the stepping circuit controlled by relay 32 to the stepping magnet *cr* of the units receiving register switch CR. This transfer takes place while the change-over switch L at the 15 calling radio station is taking two steps; so that when the switch L arrives at its second contact position, and extends the impulse circuit by way of switch arm L-² to the stepping magnet *m* of units transmitting register switch M and also places the energizing circuit of relay 67 under the control of impulse apparatus 70 by way of the switch arm L-³, the units receiving register switch CR at the called radio station is ready to take the 20 25 registration now to be transferred to it from the units receiving register switch C at the calling radio station.

The step-by-step advance of the units transmitting register switch M with its accompanying impulses of signalling intermediate frequency applied to the common carrier wave continues until the switch in its advance finds the contact identified by arm C-⁶ of the units receiving register 30 35 40 45 50 55 60 65 switch C; and each step of the switch M at the calling radio station is accompanied by a corresponding advance of the units receiving register switch CR at the called radio station. When the contact identified by arm C-³ of the units receiving register switch is engaged by the arm M-² of the switch M, relay 81 is operated, locks up to the holding ground by way of conductor 27, and shifts the impulse circuit from stepping 45 50 55 60 65 magnet *m* of switch M to stepping magnet *n* of change-over switch N. Relay 81 also at its outer right-hand armature opens the energizing circuit of the relay 67, so that thereafter until the connection is released the relay 67 remains inert and is deprived of power to open the energizing circuit of the signalling frequency applying relay 215. The continued application of signalling intermediate frequency that results from the steady closure of the energizing circuit at the back contact of relay 67, causes relay 32 at the called radio station to attract its armature steadily and maintain closed the energizing circuit of relay 124 long enough to fully operate timer 127 and open associated contacts 126 to release relay 131. The release of relay 131 disconnects stepping magnet *cr* and stops the advance of the units receiving register switch CR.

65 Thus, as a result of the operations de-

scribed in the foregoing, the receiving register switches V, BR and CR at the called radio station have been moved to positions corresponding to the positions occupied by the receiving register switches D, B and C, 70 respectively at the calling radio station. There is, therefore, at the called radio station a registration upon switch V of the particular pair of individual carrier waves that is available and is to be used, and upon 75 switches BR and CR of the tens and units digits of the called local subscriber's number. It is now necessary that a shift shall be made at both the calling and the called radio stations from the common carrier 80 wave that has heretofore been used, to the pair of individual carrier waves that has been selected; and that at the called radio station impulses shall be sent in accordance with the registration upon the tens and 85 units register switches BR and CR to cause the extension of the connection to the particular subscriber's line thus indicated.

As described, the operation of the relay 81 upon the finding of the contact point 90 identified by the units receiving register switch C extends the impulse circuit to stepping magnet *n* of switch N. When this switch takes its first step, a circuit is closed that extends from battery through the winding of stepping magnet *p* of tuning selector switch P, armature and back contact of this magnet, lower back contact and armature of relay 86, conductor 88, off-normal contacts and switch arm N-⁵, and conductor 27 to 95 ground by way of the upper front contact and armature of relay 7. Upon the closure of this circuit the stepping magnet *p* under the control of its own interrupting contacts 100 effects a rapid step-by-step advance of the switch arms of switch P. When arm P-² engages the contact point which is identified by switch arm D-⁴ of the carrier wave receiving register switch D, a circuit is closed that extends from battery through 105 the winding of relay 86, switch arms P-² and D-⁴ with the corresponding contacts upon which they are resting, and inner right-hand front contact and armature of relay 33 to ground. Relay 86 in operating 110 opens the energizing circuit of stepping magnet *p*, thus stopping the advance of the switch, closes a locking circuit for itself by way of the initially-traced path to ground over conductor 88, and applies this ground 115 to the switch arms P-³ and P-⁴ and the contacts upon which the advance of the switch has stopped them.

When the switch arms P-³ and P-⁴ have been thus advanced to the position corresponding to the position occupied by arm D-⁴ of the carrier wave register switch D, and relay 86 has been operated, a circuit is closed that extends from battery through 120 the winding of relay 199 (Fig. 5), conductor 125 130

274, thence in parallel through the three relays bridged from the common conductor 274 to whichever of the conductors 94, 95 and 96 is connected to the contact point 5 upon which arm P⁻³ is resting, and to ground by way of the upper front contact and armature of relay 86, and conductor 88, as already traced. The operation of the three relays in the particular one of the three branches closed by switch arm P⁻³ tunes the transmitting antenna system to one of the carrier wave frequencies of the particular pair that has been selected; and the operation of relay 199 included in the common 10 part of the energizing circuit opens the energizing path by way of relay 200 and conductor 273 which up to this moment has kept relays 181, 191 and 201 operated to tune the transmitting antenna system to the 15 common or calling carrier wave frequency. The release of relay 200 breaks the branches of the energizing circuits of the motor 146 that drives the plate and filament current generators and of the relay 216 which applies the guarding intermediate frequency to the carrier wave; but at the same time other branches are closed by the operation of relay 199, so that this apparatus remains energized. The result therefore of the 20 movement of arm P⁻³ of switch P and the operation of relay 86 is to withdraw the common carrier wave, and to substitute for it one of the individual carrier waves of the selected pair with its superposed guarding 25 and signalling intermediate frequencies.

In order to avoid any difficulty which might arise from closing one of the individual carrier wave tuning branches of the transmitting antenna system before the common carrier wave tuning branch is opened, the energizing path for effecting the tuning of the system to the common carrier wave is controlled at a normal contact of switch arm P⁻⁷. As a result, the tuning of the transmitting 40 antenna system to the common carrier wave frequency is withdrawn at the outset of movement of the switch P and the tuning to the individual carrier wave frequency is effected at the end of the movement of the switch P, thus preventing the transmitting system from being simultaneously tuned momentarily to two different frequencies. The relay 200 included in the energizing path for tuning the transmitting system to the common carrier wave, is so constructed 45 and adjusted that it holds closed the energizing circuits controlled at its contacts for a sufficiently long period after the opening of its circuit to give the relay 199 time to operate and maintain the closure of these circuits.

When tuning selector switch P operates as described above to withdraw the common carrier wave and apply one of the individual carrier waves of the selected pair to the 50

transmitting antenna system, it also operates to alter the tuning of the receiving antenna system from that of the common carrier wave to that of the other individual carrier wave frequency of the selected pair 55 that is now about to be sent out from the transmitting antenna system of the called radio station. When switch P moves its arms to the contact point identified by switch arm D⁻⁴ of switch D and relay 86 operates, a circuit is closed that extends from battery through the winding of relay 220 (Fig. 5), winding of relay 221, thence through the winding of one or another of the tuning relays 222, 223 and 224, depending upon which of the associated conductors 42, 43 and 44, respectively, is closed at the contact points of switch arm P⁻⁴, thence by way of lower front contact and armature of relay 86, conductor 88, switch arm N⁻⁵, and conductor 27 to ground at the upper armature and front contact of relay 7. Relay 220 in operating closes additional branches of the energizing circuits of the motor generator 60 146 and relay 216 to insure the maintained energization of these devices. Relay 221, operates, no matter which of the individual branches of the circuit is closed, to open the tuning branch of the receiving antenna system that extends through condenser 231. Whichever one of the three relays 222, 223 and 224 is included in the selected energizing path, is operated to close its associated tuning branch including condenser 232, 233, or 234. The receiving antenna system of the calling radio station is thus placed in condition to respond to the particular individual carrier wave frequency sent out by the transmitting system of the called radio station. At the same time the common carrier wave is released and made available for the use of other calling radio stations.

While the tuning of the transmitting and receiving antenna systems at the calling radio station to the selected individual or communicating pair of carrier wave frequencies has been taking place, as described above, a similar operation has been going on at the called radio station. When relay 131 (Fig. 4) releases at the conclusion of the registration of the units digit by the receiving register switch CR, a circuit is completed that extends from battery through the winding of stepping magnet p of switch P at the called radio station, lower back contact and armature of relay 79, conductor 188, off-normal contacts and switch arm V⁻³, off-normal contacts and switch arm CR², outer left-hand back contact and armature of relay 131, conductor 122, left-hand armature and back contact of relay 31, and inner right-hand front contact and armature of relay 105 to ground. The closure of this circuit causes stepping magnet p to operate.

under the control of its armature and back contact and cause the rapid advance of the switch arms to a point where the switch arm P-5 engages the contact identified by the 5 switch arm V-4 of the carrier wave receiving register switch V. When this contact is engaged, relay 79 is operated over a circuit that includes switch arms P-5 and V-4 with the corresponding contacts upon which 10 they are resting, outer left-hand back contact and armature of relay 129, conductor 122, left-hand armature and back contact of relay 31, and inner right-hand front contact and armature of relay 105 to ground. 15 Relay 79 in operating locks up over the previously-traced path to ground by way of conductor 188 and switch arm V-6, and also applies the ground connection supplied through this same conductor to the switch 20 arms P-8 and P-9. The energizing circuits closed through the switch arms P-8 and P-9, and the particular contacts upon which they have been brought to rest, effect the tuning of the transmitting antenna system and the 25 receiving antenna system of the called radio station to the frequencies of the selected pair of individual carrier waves, in the same manner as has been described in connection with the tuning of the calling radio station. 30 transmitting and receiving antenna systems by the operation of switch P. When the tuning selector switches P at the two stations have been thus moved to corresponding positions, each transmitting system is tuned 35 to produce and transmit a different carrier wave of the selected pair, and each receiving system is tuned to respond to the carrier wave that the transmitting system of the other station sends out. At the time the 40 tuning of the called station transmitting antenna system to the proper carrier wave frequency of the selected pair is effected, the transmitting antenna system is un-energized and inert. Therefore the operation of relay 45 199 upon the closure of the energizing circuit of the selected one of the tuning branches starts the operation of the motor generator outfit 146, 147 and 148 to energize the transmitting system, and operates relay 50 216 to apply the guarding intermediate frequency to the selected individual carrier wave. At the same time relay 199 closes a circuit that extends by way of the right-hand winding of relay 215 and the outer 55 left-hand front contact and armature of relay 199 to ground. This operates relay 215 to apply the other intermediate frequency to the selected individual carrier wave, this other intermediate frequency being now used for impressing the voice currents upon the selected carrier wave.

As a result of the operations described above, the calling and called radio stations are each sending out one of the carrier 60 waves of the pair that has been selected,

and are each impressing upon the transmitted carrier wave both a guarding intermediate frequency and a signaling or talking intermediate frequency, and each radio station has its receiving antenna system tuned to respond to the carrier wave that the other station is sending out and to respond to both the guarding and the signaling or talking intermediate frequency carried by the transmitted wave of the other station. 75

When the calling radio station has effected the tuning of its transmitting and receiving antennæ systems to the selected pair of carrier waves, it does not immediately establish the talking condition of the radio trunk, 80 but instead awaits the receipt of a return signal from the called radio station before establishing the talking condition. When the switch N has taken two steps and brought its arms to rest in their second 85 contact position, a circuit is closed that extends from battery through the winding of relay 60 (Fig. 2), armature and back contact of relay 61, conductor 90, second contact point and switch arm N-7, conductor 79, 90 fourth contact point and switch arm F-2, conductor 78, upper back contact and armature of relay 60, and inner right-hand front contact and armature of relay 33 to ground. Relay 60 in operating opens the initial energizing circuit at its upper back contact, and at its upper front contact closes a locking circuit to ground by way of the inner right hand front contact and armature of relay 33 95 for maintaining the energization of relay 60. The path to ground closed at the upper front contact of relay 60 causes the energization of timer 62 by way of the right-hand back contact and armature of relay 57. Timer 62 thereupon starts the inward movement of its plunger, which, if permitted to continue, will close contacts 63 and operate relay 40 to give the calling subscriber the 100 busy signal and bring about the release of the connection. But when the switch N moves to its second position, it also places relay 57 (Fig. 2) under control of the guarding frequency responsive relay 252 (Fig. 6). This circuit extends from battery through 110 the winding of relay 57, conductor 56, switch arm F-3 and its fourth contact point, switch arm N-4 and its second contact point, conductor 91, left-hand front contact and armature of relay 33, conductor 100, and, when 115 relay 252 is operated upon the receipt of the guarding intermediate frequency from the called station, by way of the front contact and armature of that relay to ground. 120

As the receiving antenna system of the calling radio station is now tuned to the individual carrier wave that the transmitting antenna system of the called radio station is adapted to send out, as soon as the switch P at the called station effects the 125 change in the tuning of that station, the re- 130

lay 252 at the calling station is energized and closes the circuit traced above, thus energizing relay 57. Relay 57 in operating opens the energizing circuit of timer 62 before the timer has moved its plunger far enough in to close contact 63; and at the same time relay 57 at its right-hand armature and front contact closes the energizing circuit of relay 61, which thereupon operates to break the locking circuit of and release relay 60. Relay 60 in releasing deenergizes relay 271, thus making the signaling and talking intermediate frequency branch of the receiving antenna circuit operative for voice current receiving purposes, and also closes the energizing circuit by way of the left-hand winding of relay 215, which, however, at this time does not produce any change in the condition of that relay, which was energized over its right-hand winding by the operation of relay 199 when the transmitting antenna system was tuned to the selected individual carrier wave frequency. When relay 57 operates in response to the guarding intermediate frequency received from the called station, it closes a circuit that extends from battery through the winding of stepping magnet n of switch N, armature and back contact of that magnet, switch arm N^{-3} and its second contact, conductor 77, and left-hand front contact and armature of relay 57 to ground. As a result, switch N moves its arms one more step to their third contact position. This closes a circuit that extends from battery through the winding of relay 87 (Fig. 2), conductor 89, and third contact point and switch arm N^{-6} to ground, thus operating relay 87 and closing the circuit of the radio trunk through to the two way repeating coil 149 and its associated apparatus. This places the calling subscriber's telephone line in communicating relation with the transmitting and receiving antenna systems of the calling radio station.

Returning now to the operations that are taking place at the called radio station, the release of relay 131 at the conclusion of the units registration upon switch CR not only operates tuning selector switch P to tune the called radio station to the selected pair of carrier waves, but also closes a circuit that extends from battery through the winding of relay 140 (Fig. 4), back contact and armature of relay 141, outer left-hand back contact and armature of relay 137, off-normal contacts and switch arm CR^{-2} , outer left-hand back contact and armature of relay 131, conductor 122, left-hand armature and back contact of relay 31, and right-hand front contact and armature of relay 105 to ground. Relay 140 in operating energizes relay 141, and that relay in operating breaks the energizing circuit of relay 140. The two relays therefore constitute an interrupter, the interaction being so adjusted as to make and break the circuits controlled by the armatures of relay 140 at the normal stepping rate of automatic switches. Each time relay 140 attracts its armatures it opens at its right-hand armature and back contact the energizing circuit of the relay 107, which thereupon breaks the bridge of branch RT^{-2} of the radio trunk by way of conductors 17 and 18 and thus causes the automatic switch 41 to which branch RT^{-2} has been extended through line switch 13 to take one step in a manner that is well understood in the art. At the same time relay 140 in operating closes a circuit that extends from battery through the winding of stepping magnet w of tens transmitting register switch W, right-hand back contact and armature of relay 137, left-hand winding of relay 132, switch arm W^{-1} and its normal contact, right-hand front contact and armature of relay 140, front contact and armature of relay 170, and thence to ground over the previously traced path by way of conductor 122 and contacts of relays 31 and 105. Upon the operation and release of stepping magnet w switch W takes one step, thus breaking the initial energizing circuit by way of arm W^{-1} ; but the operation of relay 132 maintains the energizing circuit of the stepping magnet w at the inner left-hand front contact and armature of the relay. Relay 132 in operating closes a locking circuit for itself by way of its right-hand winding and inner right-hand front contact and armature, and to ground at the normally closed inner contacts 135 of timer 136. Upon the release of the interrupter relay 140 a circuit is closed that extends from battery through the winding of relay 133, outer normally closed contacts 134 of timer 136, outer right-hand front contact and armature of relay 132, and left-hand back contact and armature of relay 140 to ground. The operation of relay 133 energizes timer 136 to start the inward movement of its plunger. This breaks the initial energizing circuit of relay 133 by way of timer contact 134; but the energizing circuit of relay 133 is maintained closed at the left-hand armature and front contact of this relay as long as the relay 140 is released.

Interrupter relay 140 continues intermittently to attract and retract its armatures, and each attraction and retraction causes both the automatic connector switch 41, to which the radio trunk has been extended by way of line switch 13, and the tens transmitting register switch W to take one step. With the step of the switch W that moves its arm W^{-4} into engagement with the contact identified by the switch arm BR^{-4} of the tens receiving register switch, a circuit is completed that extends from battery through the winding of relay 137, switch arms W^{-4} and BR^{-4} with the corresponding contacts upon

- which they are resting, outer left-hand back contact and armature of relay 130, and thence to ground by way of conductor 122. Relay 137 in operating locks up by way of 5 its inner left-hand front contact and armature and to ground over conductor 122, and at its right-hand back contact and armature opens the interrupter circuit to stepping magnet ω , thus bringing switch W to rest.
- 10 At its outer left-hand back contact and armature, relay 137 opens the energizing circuit of the interrupter relay 140, and that relay thereupon becomes inert, with the result that the steady closure of its left-hand 15 back contact and armature holds the energizing circuit of relay 133 closed long enough to permit the timer 136 to effect the full inward movement of its plunger and open the associated inner contacts 135. Upon 20 the opening of these contacts the locking circuit of relay 132 is broken; and that relay in releasing re-establishes by way of its outer left-hand armature and back contact and the outer left-hand front contact and 25 armature of relay 137, the energizing circuit of the interrupter relay 140. At the same time relay 132 in releasing closes a circuit that extends from battery through the stepping magnet ω of the units transmitting register switch Z, right-hand back contact and armature of relay 138, left-hand winding of relay 139, switch arm Z^{-1} and its normal contact, off-normal contacts and switch arm W^{-2} , inner left-hand back contact 30 and armature of relay 132, and right-hand front contact and armature of relay 140 to ground when that relay operates.
- The closure of the two above-traced circuits upon the release of relay 132 again 40 causes the intermittent operation of the interrupter relays 140 and 141, and gives them control over the line connector switch to which the trunk has been extended, and over the units transmitting register switch Z and 45 its associated apparatus. The operation of the switch Z is like that of switch W as described above. Upon each energization of the interrupter relay 140 relay 107 is released to cause a stepping impulse to pass 50 to the connector switch to which the trunk has been extended, while at the same time the stepping magnet ω of the units transmitting register switch Z is energized; and upon each deenergization of the relay 140 55 the stepping magnet ω is deenergized to cause the switch to take one step, and the relay 133 is operated by way of the outer right-hand armature and front contact of relay 139 to start the inward movement of the plunger of 60 timer 136. When the contact identified by switch arm CR^{-4} of the units receiving register switch CR is encountered by switch arm Z^{-4} , the relay 138 is operated, locks up to the holding ground over conductor 122, 65 breaks at its outer left-hand armature and
- back contact the energizing circuit of the interrupter relay 140, and breaks at its right-hand armature and back contact the energizing circuit of the stepping magnet ω . The continued deenergization of interrupter 70 relay 140 energizes relay 133 for a sufficient length of time to cause the complete operation of the timer 136, and the resultant opening of the timer contacts 135 releases relay 139. When relay 139 releases, a circuit is 75 closed that extends from battery through the winding of relay 87 (Fig. 2), conductor 89, switch arm V^{-5} , switch arm Z^{-2} , outer left-hand armature and back contact of relay 139, switch arm CR^{-2} , outer left-hand back 80 contact and armature of relay 131, and conductor 122 to ground. Relay 87 in operating completes the talking circuit of the trunk to the two-way repeating coil 149 and its associated apparatus, and thus places the trunk 85 in communicating relation with the associated transmitting and receiving antenna systems of the called radio station.
- The impulses transmitted to the branch 90 RT $^{-2}$ of the trunk by the operation of the tens and units transmitting register switches W and Z, as has been described, extends the trunk to the called subscriber's line. The apparatus and circuits for effecting this extension in response to the transmitted impulses, and for returning a busy signal if the called line is busy, and for applying ringing current to the called subscriber's line if the line is available for connection, are well 95 known in the art and need not be described.
- If the called line is found to be busy, the 100 calling subscriber will be apprised of that fact by the receipt of the usual busy tone transmitted from the usual source at the connector switch, or elsewhere in the system to which the called line has connection, back over the voice conductors and through the radio link to the talking conductors of the calling subscriber's station. The path over 105 which this busy tone is transmitted is the same as that, heretofore traced, over which the voice is transmitted, and includes the two modulators associated respectively with the talking intermediate frequency oscillator and with the radio frequency oscillator at the called radio station, and at the calling radio station it includes the two detectors for the radio wave and the talking intermediate frequency wave respectively, together 110 with associated amplifiers and the like.
- When the subscriber at the called line substation responds to the ringing of his bell and removes the telephone receiver from its hook, conversation may proceed between the calling station and the called station through 115 the medium of the conductive connections of the stations with their respective radio trunks, and the radio connection of these trunks with each other, the voice currents 120 being produced and propagated in the man-

ner described in a preceding portion of this specification.

The release of the connection is under the control of the calling subscriber. When the calling subscriber opens his line circuit by replacing his telephone receiver upon its hook, the continuing deenergization of the line relay 6 brings about the deenergization of the slow releasing relay 7. Relay 7 in releasing opens at the front contact of its upper armature the paths by way of conductors 26 and 27 that have served to hold the connection, and at the back contact of its upper armature it closes a circuit by way of conductor 29 for effecting the restoration of the various receiving and transmitting register switches. In opening at its upper front contact and armature the holding path by way of conductor 27, relay 7 in releasing effects the release of relays 76, 80 and 81, and opens the one of the paths over which relays 85 and 86 (Fig. 2) are maintained energized. The relays 85 and 86 have other holding paths controlled by switch arms D⁻³ and D⁻⁴, respectively, of switch D, so that the release of these two relays is not solely controlled by the breaking of the path by way of conductor 27. But on account of the immediate restoration of switch D to normal upon the release of relay 7, as will be described, the relays 85 and 86 release at substantially the same time that the other relays controlled by holding conductor 27 release.

In opening at its upper armature and front contact the energizing path by way of conductor 26, relay 7 deenergizes relay 31, which thereupon releases relay 33. Relay 31 in releasing closes a circuit that extends from battery through the winding of stepping magnet *p* of tuning selector switch P, armature and back contact of this magnet, off-normal contacts and switch arm P⁻¹, conductor 93, winding of relay 21, outer right-hand back contact and armature of relay 116, and right-hand back contact and armature of relay 31 to ground. This causes the stepping magnet *p* to act under the control of its own contacts to step the arms of switch P on around to normal, the arrival of arm P⁻¹ at normal breaking the circuit of the stepping magnet. The restoration of the switch arms P⁻³ and P⁻⁴ to normal deenergizes whichever of the sets of relays has been held operated to tune the transmitting and receiving antennæ circuits to the selected individual pair of carrier waves; and the return of the switch arm P⁻¹ to normal prepares a path for the tuning of the transmitting antenna system to the common carrier wave frequency when the radio trunk is again seized by a local calling line. The release of relays 199 and 220 (Fig. 5), which occurs upon the interruption of the individual transmitting and receiving system tuning

circuits at switch arms P⁻³ and P⁻⁴, respectively, opens the energizing circuits for the carrier wave and intermediate frequency generating and controlling devices of the transmitting system. At the same time the relay 221, which is included serially in the common part of the receiving antenna tuning circuit, is released to reestablish the tuning of the receiving antenna to the common or calling carrier wave. At the time that the switch P is restored to normal the associated relay 86 has been released by the interruption of its energizing circuit at the upper front contact of relay 7 (Fig. 1), so that the switch arms P⁻³ and P⁻⁴ are disconnected from ground, and in their passage over the contact terminals of their tuning branches of the transmitting and receiving antenna systems during the return movement do not cause the momentary tuning of the station to other frequencies some of which may be in use.

As has been stated, when relay 31 is deenergized by the release of relay 7, it releases relay 33. Relay 33 in releasing disconnects the controlling contacts of the signalling frequency relay 268 and the guarding frequency relay 252 from the extensions over which these relays have transmitted the return signals for the control of the impulse transmitting apparatus, and connects them with their extensions to the relay 32 and the relay 115. Relay 33 in releasing also opens at its inner right-hand front contact and armature the path to ground which maintains energized the relay 215 for applying the signaling intermediate frequency to the carrier wave, thus releasing that relay. As the relay 216 for applying the guarding intermediate frequency and the apparatus 146, 147 and 148 for supplying current for generating the carrier waves and their intermediate frequencies have also been deenergized, as previously described, the transmitting antenna system is now inert.

As previously stated, when relay 7 is released upon the hanging up of the calling subscriber's receiver, it closes at its upper back contact and armature a path by way of conductor 29 for restoring the various switches. The first switch to be restored is the station register switch A, the restoring circuit being from battery through the winding of the stepping magnet *a*, and armature and back contact of this magnet, off-normal contacts and switch arm A⁻⁴, conductor 29, winding of relay 20, and upper back contact and armature of relay 7 to ground. When the station register switch A has been fully restored, the restoring conductor 29 is extended by way of switch arm E⁻¹ and off-normal contacts of the station transmitting register switch E to stepping magnet *e* of that switch. When the switch

E has been restored, the restoring circuit is extended by way of switch arm E-1 and its normal contact to switch arm F-8 and stepping magnet f of the change-over switch F. After restoring this switch the restoring circuit is extended to the carrier wave transmitting register switch G, then to the associated change-over switch H, then to the tens receiving register switch B, then to the tens transmitting register switch K, then to the associated change-over switch L, then to the units receiving register switch C then to the units transmitting register switch M, and finally to the associated change-over switch N. The stepping magnets of all these switches are successively energized in the order named to bring about the restoration to normal of the associated switch arms. There is also a branch of the restoring conductor 29 that extends by way of off-normal contacts and switch arm D-5 to the stepping magnet d, which magnet therefore acts immediately upon the release of the relay 7 to restore the carrier wave selecting switch D. The switch restoring circuit by way of conductor 29 includes the winding of relay 20, and the switch restoring circuit that is closed at the right-hand back contact of relay 31 upon the release of that relay includes the winding of relay 21. These two relays control branches of an energizing circuit for operating the relays 19 (Fig. 1) and 124' (Fig. 2). As long as either one of the relays 20 or 21 is energized by the closure of its associated circuit during the restoration of the switches, the relay 19 is operated to maintain the busy condition upon the various terminals of the radio trunk R and thus prevent the trunk from being seized, and the relay 124' is energized to deprive the relay 115 and 32 of their control over the associated circuits. This is so that if the connection is released at a time when the common carrier wave is in use in establishing a connection between other stations, the relay 32 may be rendered ineffective to control the station selecting switch AR in response to the signal impulses received by the relay 268; and so that the relay 115 may be prevented from responding to the guarding intermediate frequency relay 252 to operate the relays 116 and 105. If the relay 116 were permitted to operate under these circumstances it would open the restoring circuit closed by the release of relay 31, and in conjunction with relay 105 would partially establish the call receiving circuit connections. When relay 124' operates it closes at its inner lower front contact and armature a path including the winding of the relay that is adapted to be completed at the outer lower armature and contact of relay 115 if that relay is energized. As a result, if the release of the radio trunk that has been in use and the restoration of its switches is completed at a time when the common carrier wave is in use by some other station, the condition of response of the relay 115 to the guarding intermediate frequency of the common carrier wave holds relays 124' and 19 operated until the other station has completed its sending operation and has released the carrier wave. This prevents the radio trunk that has been in use from becoming responsive at an intermediate stage of the sending operation of some other radio station or from becoming selectable at one of its local terminals and from thus having its associated apparatus improperly operated. Upon the final release of relays 19 and 124', the restoration of the calling station radio trunk to normal is completed and the trunk is available for either an incoming or outgoing call.

As has been stated, the release of the connection at the called radio station is under the control of the calling radio station. As long as the guarding intermediate frequency is applied to the carrier wave at the calling radio station, the guarding frequency responsive relay 252 at the called radio station is held energized. When the guarding intermediate frequency at the calling radio station is withdrawn as a result of the release of the connection, relay 252 at the called radio station is released and opens the energizing circuit of relay 115. Relay 115 in releasing opens the initial energizing circuits of the relays 116 and 105. At its upper back contact, relay 115 closes a circuit for energizing relay 117, this circuit extending from battery through the winding of relay 117, outer resting contact 119 of timer 118, outer left-hand front contact and armature of relay 116, upper back contact and armature of relay 115, and inner upper armature and back contact of relay 124' to ground. At the same time relay 115 in releasing closes a circuit that extends from battery through the winding of relay 102, outer resting contact 103 of timer 101, outer left-hand armature and front contact of relay 105, inner lower back contact and armature of relay 115, outer upper armature and back contact of relay 124', and right-hand back contact and armature of relay 31 to ground. The protracted energization of relays 117 and 102 by the continuing deenergization of relay 115 causes the associated timers 118 and 101 to draw in their plungers until the associated contacts 120 and 104 are operated and the locking circuits of relays 116 and 105 thus broken. When this occurs both relays release, and in releasing open the locking circuits of relays 117 and 102, which relays thereupon also release and deenergize their associated timers 118 and 101.

When relay 105 releases it breaks the holding path by way of conductor 122, and brings about the release of relays 170, 172,

128, 138, 137 and 173. The opening of this holding path also removes the ground that has been applied by way of outer left-hand armature and back contact of relay 131, 5 switch arm CR⁻², switch arm V⁻⁶, conductor 188 and the armatures and front contacts of relay 79 to the tuning circuit controlling switch arms P⁻⁸ and P⁻⁹.

The release of relay 170, as a result of the 10 release of relay 105, opens the circuit of relay 107, which relay in releasing breaks the bridge of the branch RT² normally closed by way of conductors 17 and 18. In accordance with the well understood operation of 15 automatic telephone systems, the breaking of this bridge releases the line switch 13 and the other automatic switches through the medium of which the radio trunk has been extended to the called subscriber's line, the 20 release of the line switch 13 causes the release of relay 11 and the reestablishment of the circuits it controls, also the release of relay 8. Relay 8 in releasing releases relay 10 to switch the radio trunk RT from its 25 branch RT² to its branch RT'. The release of relay 8 also removes the busy test condition from the test conductors of the trunk terminals 4 and 14; but at the same time re-establishes an energizing path for the relay 30 5 by way of inner left-hand back contact and armature of relay 9, outer left-hand back contact and armature of relay 8, and front contact and armature of the slow release relay 19. As will be described, the relay 19 is at this time energized, and remains 35 energized until the connection has been completely released. Relay 5 in operating places the busy test condition upon the terminals 13 and 14 of the trunk; and as the operation 40 of relay 19 to energize relay 5 has also made terminal 4 of the trunk test busy, the trunk is prevented from seizure or further use until the connection is completely released.

When relay 116 releases it closes a circuit 45 that extends from battery through the winding of stepping magnet p of switch P, armature and back contact of this magnet, off-normal contacts and switch arm P⁻¹, conductor 93, winding of relay 21, outer right-hand 50 back contact and armature of relay 116, and right-hand back contact and armature of relay 31 to ground. This causes the stepping magnet p to act under the control of its own contacts to step the switch arms of the associated switch P around to normal. As the 55 return movement of the switch arms of which P starts, the relay 79 is deenergized by the release of relay 105, as has been described, so that the wipers P⁻⁸ and P⁻⁹ are disconnected 60 from ground during their passage over their associated contact points, and are unable to effect the energization of the tuning circuits over which they pass. The wipers P⁻⁸ and P⁻⁹ in returning to normal withdraw 65 the individual carrier wave from the trans-

mitting antenna system of the called radio station, and also, by breaking the individual carrier wave tuning circuit, change the tuning of the receiving antenna system from that of the selected individual carrier wave 70 to that of the common carrier wave.

When the switch arm P⁻¹ reaches its normal position, it extends the restoring path of conductor 93 by way of conductor 92 and inner right-hand armature and back contact 75 of relay 128 to the stepping magnet ar of switch AR. This causes the switch AR to restore, and upon the completion of its restoration the restoring circuit traced above is extended to the stepping magnet of switch 80 Y, thence to the stepping magnet of switch V, thence to the stepping magnet of switch BR, thence to the stepping magnet of switch W, thence to the stepping magnet of switch CR and finally to the stepping magnet of switch Z. As the restoring circuit is extended to one after the other of these stepping magnets, it brings, about the restoration of each associated switch.

As long as the restoring path by way of conductor 93 is closed and the process of restoration of the switches is going on, the relay 21 included in the restoring circuit is energized, and in operating causes the operation of the slow-release relays 19 and 124'. 90 As has previously been noted, the operation of relay 19 during the restoration of the switches maintains the busy test condition upon the terminals 4, 13 and 14 of the radio trunk. The operation of relay 124', as was described in connection with the releasing operation at the calling radio station, makes the relays 115 and 32 ineffective to control their associated apparatus in case the release of the connection is taking place at a time when the common carrier wave is in use by some other radio station. When the last of the series of switches at the called radio station has been restored to normal, 100 as has been described, relay 21 is deenergized to release relays 19 and 124', thus completing the restoration of the radio trunk to its normal condition. The release of relay 124', however, is subject to the control of relay 115 by way of the locking circuit of relay 124'. 110 As a result, if the process of restoring the trunk to normal is completed at a time when the common carrier wave is in use by some station, the relays 124' and 19 are held energized to prevent relays 115 and 32 from exercising their call receiving functions and to prevent the trunk from being seized by a local calling line until the common carrier wave is withdrawn and relay 115 released.

In the foregoing description no specific location has been assigned to the radio or high frequency stations of the system. These stations may be located at widely separated points, and each may have associated with it a plurality of local stations constituting an 120 125

- exchange, between which exchanges interconnection is had through the medium of the associated radio trunks. But, if desired, two or more radio trunks or high frequency stations may be associated with and available to the local stations of each exchange system, so that the local station of any exchange may have two or more means of access to a local station of another exchange.
- 10 In such case, if one of the trunks is in use communication may be established by way of another of the trunks serving the local stations of the calling exchange; and the selected trunk at the calling exchange may then be operated to establish connection with one or another of the trunks associated with the called exchange. The procedure under these circumstances would be for the calling subscriber, upon receiving the busy signal informing him that the first tried trunk of the called exchange is in use, to hang up and then initiate a second call which he would dial in such a manner as to try another of the trunks serving the local stations of the called exchange. Upon the appropriation of a trunk that is found not in use, that trunk is tuned to the previously-selected channel or pair of carrier waves in the manner hereinbefore described.
- 20
- 30 In the preferred embodiment of the invention as described in the foregoing, the common or calling carrier wave is employed not only for conveying the impulses that effect the selection of the called station and the setting of its register to the selected pair of communicating waves, but also for conveying the impulses that set the called station tens and units receiving register switches to correspond with the setting of the like register switches at the calling station. But it will be apparent that, if it should be desired to do so, by a simple and obvious rearrangement the transmission of the tens and units register impulses may be effected over the communicating wave pair, the release of the common carrier wave and the tuning of the calling and called stations to the selected pair of communicating carrier waves thus being permitted immediately after the transmission of the impulses that determine the pair of communicating waves to be used, and the balance of the register controlling impulses being then conveyed over the selected pair.
- 40
- 50 It will be understood that by use of a wire or conductive connection between the two various stations for guiding the high frequency waves or oscillations between these stations, in place of the unguided transmissions of the waves or oscillations through space, as herein disclosed, the present system may be employed as a system of wire communication.
- 60
- 65 Since the apparatus at the various stations would be of the same nature, whether

the system were a high frequency wire system or a radio system, the claims are intended to cover systems of both types. In general, the frequencies employed on a high frequency wire line or a carrier line, would be lower than the numerical values hereinbefore given. These values, however, are given merely as examples, and frequencies much lower than these could be used in a radio system, if desired. By "high frequency" is meant a frequency high as compared with the frequency of the signal which is transmitted by the high frequency wave and no limiting values can be given. It may be said, however, that for satisfactory high frequency telephony the frequency of the carrier wave should be near or above the upper limit of audibility and frequencies from about 10,000 cycles upwards have proved satisfactory in practice. For telegraphy or other types of signaling employing lower frequencies than telephony, still lower carrier frequencies can be used. For convenience the frequency of the signaling currents themselves, such as voice currents, telegraph currents or other signaling currents are sometimes referred to as low frequencies to distinguish them from the high frequencies or carrier frequencies.

In order fully to disclose the present invention in its preferred form it has been convenient to make use of certain features in connection with the production and propagation of high frequency waves that are the subject of co-pending applications of various inventors, assigned to the assignee of the present application. Such features are disclosed and claimed in the United States patent to Hartley 1,356,763, issued October 26, 1920; and in the application of Raymond A. Heising, Serial No. 81,980, filed March 3, 1916 and in the United States patent to Heising 1,442,147, issued January 16, 1923. Other features made use of in the present disclosure are disclosed and claimed in the application of Samuel B. Williams, Jr., and Lewis M. Clement, Serial No. 370,476, filed April 1, 1920. These features, as has been stated, are disclosed and claimed in the above mentioned applications, and no claim is made to them in the present application.

What is claimed is:

1. The combination with a plurality of high frequency stations each having associated communicating apparatus, of means at said high frequency stations for producing and utilizing a plurality of pairs of high frequency waves and automatic means at said high frequency stations for bringing the communicating apparatus of any two of said stations into operative relation through the medium of any of said pairs of high frequency waves.

2. In a high frequency communicating

system comprising a plurality of high frequency stations, the combination with means at one of said stations for generating a plurality of high frequency waves any one of which may be used in establishing communication between said station and any other of said stations, of means for automatically selecting an idle one of said high frequency waves, and means for utilizing the selected wave for communicating with the desired station.

3. In a communicating system comprising a plurality of high frequency stations, the combination with means at one of said stations for producing a plurality of high frequency waves any one of which may be used in providing operative relation between said station and any other of said stations, of a local subscriber's line having a switchhook at the substation thereof, means under the control of said switchhook for extending said line to the associated high frequency station and causing the automatic selection of an idle one of said high frequency waves, and means including the means for producing the selected wave for providing operative relation between said local telephone line and another of said high frequency stations.

30 4. The combination with a high frequency station having means for producing a plurality of high frequency waves any one of which may be used as a medium of communication between said station and another high frequency station, of a local telephone line associated with said high frequency station, and means made operative upon the initiation of a call by said local telephone station for extending said line to the associated high frequency station and automatically selecting an idle one of said high frequency waves for communicating purposes.

45 5. The combination with a calling high frequency station and a called high frequency station, of means at said calling station for producing a plurality of high frequency waves any one of which may be used for communication between said calling station and said called station, a local telephone line connected with said calling high frequency station and provided with a switchhook at the local substation thereof, means controlled by said switchhook for effecting the automatic selection by said calling high frequency station of an idle one of said high frequency waves and means for utilizing the selected wave for communicating between said local telephone line and said called high frequency station.

60 6. The combination with a calling high frequency station and a called high frequency station, having means for generating and responding to a plurality of pairs

of high frequency waves any one of which 65 may be used for communication between said stations, of a plurality of local telephone lines associated with each station, means controlled in the initiation of a call by a local telephone line associated with the 70 calling high frequency station for automatically selecting an idle pair of high frequency waves for use in communication between said calling high frequency station and said called high frequency station, and selecting switch mechanism at the called high frequency station under the control of the local telephone line associated with said calling high frequency station for bringing the called high frequency station into communication with a particular one of the associated local lines, and thereby establishing communication between the local line of the calling station and the selected local line of the called station.

7. In a communicating system having a plurality of high frequency stations, the combination with means at one of said stations for generating and transmitting a plurality of high frequency waves any one of which may be used as a medium of communication between said station and a desired one of the other stations, of means for automatically selecting an idle one of said high frequency waves and utilizing the same for communicating with the desired station, and automatic means for preventing any other high frequency station from transmitting the selected high frequency wave.

8. In a communicating system comprising a plurality of high frequency stations, the combination with means at said stations for producing, transmitting and utilizing a plurality of pairs of high frequency waves less in number than the number of stations in the system, automatically operating means at each of said high frequency stations for selecting an idle pair of said waves and employing the same for communicating with any desired one of said other high frequency stations of the system, and means for preventing the other high frequency stations from employing the selected pair of waves while it is in use.

9. In a communicating system, the combination with a plurality of high frequency stations, of means at each station for enabling said station to produce and receive respectively the individual waves of any one of a plurality of pairs of high frequency waves for communication with any other of said stations and means for automatically excluding any calling station from the use of a pair of high frequency waves that is in use by any other of said high frequency stations.

10. In a communicating system, the combination with a number of high frequency

- stations, of means at each of said stations for producing and receiving respectively the two waves of each of a lesser number of pairs of high frequency waves, means at 5 each of said high frequency stations for appropriating one of said pairs of high frequency waves for its use, and means at each calling station for preventing that station from utilizing a pair of high frequency 10 waves that has been appropriated by any other of said high frequency stations.
11. The combination with high frequency stations each having means for producing and responding to a plurality of high frequency waves, of automatic means at one 15 station for successively tuning said station to one after another of said waves, a receiver at said one station, and means operated due to the failure of said receiver to 20 respond to a particular one of said waves for setting said station for the subsequent use of said wave.
12. The combination with means for producing a plurality of different high frequency waves, of a station having a high frequency receiving system, automatic switching means for progressively changing the tuning of said high frequency receiving system to become responsive to one 25 after the other of said waves, means controlled by the response of the high frequency receiving system of said station for controlling said automatic switching means, and means dependent upon the failure of said 30 receiving system to respond for disabling said switching means.
13. The combination with means for producing a plurality of different high frequency waves, of a high frequency station 35 having a high frequency receiving system, tuning switch mechanism adapted in its operation to tune said receiving system to one after another of said different waves, means responsive to each wave as the receiving system is brought into tune therewith for controlling the operation of said tuning mechanism, a high frequency transmitting system, and means controlled in accordance 40 with the operation of said tuning mechanism for tuning said high frequency transmitting system.
14. The combination with a plurality of high frequency stations, each having means for transmitting and receiving high frequency waves of different frequencies, including a wave responsive device, of means at each high frequency station for automatically tuning the receiving antenna of the station successively to various of the wave 45 frequencies it is adapted to receive, means responsive to the frequency to which the receiving antenna is tuned for causing the receiving antenna to be tuned to the next frequency, and means made operative by the 50 failure of said wave responsive device to operate to cause the high frequency station to select the corresponding frequency for communicating purposes.
15. The combination with a plurality of stations, each having a high frequency receiving and a high frequency transmitting system, of means at said stations for producing and utilizing a plurality of pairs of high frequency waves for communicating between said stations, and automatic means 55 for selecting for use between two of said stations a pair of high frequency waves that is not at the time in use between others of said high frequency stations.
16. The combination with a plurality of high frequency stations, of means at said stations for producing and utilizing a lesser number of pairs of high frequency waves than there are stations in the system, and means at each station for testing and selecting for use one of said lesser number of pairs of high frequency waves that is not at the time in use by another of said high frequency stations.
17. The combination with a station having means for transmitting and receiving a plurality of high frequency waves, of selecting switching mechanism for controlling the selection of a particular one of said waves for use by said station in receiving, 60 another high frequency station, high frequency wave producing and controlling means at said other high frequency station for controlling said selective switching mechanism at said first-mentioned station, 65 and means controlled by said selective switching mechanism for setting the transmitting means at said first station to transmit a wave of a frequency dependent upon the particular one of said waves selected for 70 use in receiving.
18. The combination with two stations, each having high frequency generating means, of tuning means at one of said stations for tuning said high frequency generating means to generate and transmit any 75 desired one of a plurality of high frequency waves, and means at the other station for controlling said tuning means.
19. The combination with a station having high frequency receiving apparatus and high frequency transmitting apparatus, of means for effecting the selective tuning of said transmitting apparatus under the control of said receiving apparatus, and another 80 station having means for generating and transmitting a high frequency wave for controlling the tuning of the transmitting apparatus of said first-mentioned station.
20. The combination with a station having high frequency receiving apparatus and high frequency transmitting apparatus, of means controlled by said receiving appara- 85

- tus for effecting the selective tuning of said transmitting apparatus, another station having means for generating and transmitting a high frequency wave to which the receiving apparatus of said first-mentioned station is responsive, and means at said other station for controlling said wave to bring about the selective tuning of the transmitting apparatus of said first-mentioned station.
21. The combination with a calling station and a called station, each having high frequency receiving apparatus and high frequency transmitting apparatus adapted for selective tuning to different wave lengths, of means for tuning the transmitting and receiving apparatus of said calling station to certain wave lengths, and means at said called station under the control of said calling station for tuning the high frequency receiving and high frequency transmitting apparatus of said called station to corresponding wave lengths.
22. The combination with a calling station and a called station each provided with high frequency transmitting apparatus and high frequency receiving apparatus, of means for selecting a pair of waves and tuning the high frequency transmitting apparatus of said calling station to one wave and the high frequency receiving apparatus to the other wave of the selected pair, and means under the control of said calling station for tuning the receiving apparatus of the called station to the wave to which the transmitting apparatus of the calling station is tuned, and for tuning the transmitting apparatus of the called station to the wave to which the receiving apparatus of the calling station is tuned.
23. The combination with two stations each provided with means for producing and utilizing a plurality of high frequency waves, of selective switching mechanism at each station for controlling the selection of any desired one of said waves for use by the associated station, and means at one of said stations for controlling the selective switching mechanisms of both of said stations to select corresponding waves adapted for establishing communicating relations between said stations.
24. The combination with a plurality of stations each provided with means for producing and utilizing a plurality of high frequency waves, of selective switching mechanism at each station for selecting any desired one of said waves for employment by that station, testing means made operative in the initiation of a call by one of said stations for testing and selecting high frequency waves not in use by other stations, and means controlled by said testing device for controlling the operation of said selective switching mechanisms at the calling station and at the station that is being called.
25. The combination with a plurality of stations having means for producing and utilizing a plurality of pairs of high frequency waves any pair of which may be used in communicating between a calling station and a desired one of the other stations, of means at the calling station for automatically selecting an idle pair of said high frequency waves, and selective switching mechanism at the calling and called stations under the control of said automatic selecting means and adapted to tune said calling and called stations to the selected pair of high frequency waves.
26. The combination with a plurality of stations having means for producing and utilizing a plurality of pairs of high frequency waves any pair of which may be used for communicating between a calling station and a desired one of the other stations, of means at the calling station for automatically selecting an idle pair of said high frequency waves, means under the control of the calling station for selecting another high frequency station, and means under the control of said automatic wave selecting means for placing the calling station and the called station in communicating relation through the medium of the selected pair of high frequency waves.
27. The combination with a plurality of stations, each having means for producing and responding to a plurality of different high frequency waves any one of which may be used for enabling any station to communicate with any other station, of a register switch at a calling one of said stations, means at said calling station for selecting an idle one of said high frequency waves and operating said register switch to register the selected wave, a register switch at the station that is being called, means under the control of the calling station register switch for causing the called station register switch to receive a like registration, and means under the control of said register switches for tuning the calling station to produce and the called station to respond to the selected high frequency waves.
28. The combination with two stations each having means for producing and responding to a plurality of high frequency waves any pair of which may be used for effecting two-way communication between said stations, of means for selecting for use a particular pair of said waves, and automatically controlled switching mechanism at each station for tuning that station to produce a different wave of the selected pair and to respond to the wave produced by the other station.
29. The combination with a calling sta-

tion and a called station each having means for producing and responding to a plurality of high frequency waves, of means made operative at the calling station for 5 selecting an idle pair of said waves for communicating purposes, means controlled at the calling station for tuning both the calling station and the called station to the selected pair of waves, switching mechanism 10 at each station selectively operated according to whether the station is calling or called, and means controlled by said switching mechanism for controlling the tuning of the associated station to produce one 15 wave of the selected pair and respond to the other wave of the selected pair when the station is calling, and to produce the second-mentioned wave and respond to the first-mentioned wave when the station is 20 called.

30. The combination with a plurality of high frequency stations, of means for producing and utilizing a high frequency wave, switching mechanisms at said stations simultaneously and correspondingly operated by said wave, means controlled by the relative degree of operation of said switching mechanisms at the various stations for selecting one of said stations and excluding the others, 35 and communicating apparatus at each station rendered responsive to further control by said wave in case the associated station is the selected station.

31. The combination with a plurality of 35 idle high frequency stations, of a calling high frequency station having means for producing and controlling high frequency waves, switching mechanism at each of said idle stations adapted to be simultaneously 40 and correspondingly advanced under the control of said waves, communicating apparatus at said calling high frequency station and at each of said high frequency stations, and means made operative by the degree 45 of operation of said switching mechanisms at the various idle stations for establishing operative relation between the communicating apparatus of the calling station and the communicating apparatus of a particular one of said idle stations and excluding the communicating apparatus of the other stations.

32. The combination with a plurality of 55 idle high frequency stations, of a calling high frequency station having means for producing a high frequency wave, means at said calling station for transmitting controlling impulses through the medium of said wave, selective switches at said idle 60 high frequency stations correspondingly advanced step by step by said impulses, and means at the respective idle stations automatically operated upon the termination of said impulses for rendering one of said stations responsive and all of the other idle

stations unresponsive to further selective control from said calling station.

33. The combination with a plurality of stations, each having means for producing and utilizing a calling high frequency wave, 70 of station-selecting apparatus at each station normally responsive to the production of said calling high frequency wave at any other station, means responsive to the busy condition of any of said stations for rendering the associated station-selecting apparatus unresponsive to the calling wave, means controlled by the station-selecting apparatus at all said stations that are not busy for excluding all but one of said non-busy stations in response to the production and control of said calling wave at a calling station, and apparatus at the selected station responsive to further control by the calling wave transmitted from the calling station. 75

34. The combination with a plurality of stations, each having means for producing and utilizing a calling high frequency wave, 80 of station-selecting apparatus at each station normally responsive to the production of said calling high frequency wave by a calling station, means for controlling said calling high frequency wave at said calling station to select one of said stations and exclude the other stations, switching apparatus at the selected station responsive to said calling wave, like switching apparatus at the excluded stations, and means for holding said switching apparatus of the excluded stations unresponsive to said calling wave 90 until said wave is withdrawn.

35. The combination with a plurality of stations, of means at each station for establishing high frequency wave communication with the other stations, means for producing a calling high frequency wave, 95 switching mechanism at each station responsive to said wave, means for rendering said switching mechanism unresponsive to said wave when the associated station is busy, and means at each station controlled by said calling wave for preventing the switching mechanism of said station from becoming responsive to said wave if said station becomes idle while said wave is applied. 105

36. The combination with a plurality of stations, of high frequency communicating means at each station, switching mechanism at each station responsive to a calling high frequency wave, means for producing and transmitting said calling wave to control said switching mechanism of the various stations to establish communicating relation between them, means for rendering the switching mechanism of a station unresponsive to said calling wave when the communicating relation at that station has been established, means for restoring each station to render its switching mechanism again responsive to said calling wave, and means 120 125 130

operative during the application of said calling wave for preventing the operation of said restoring means.

37. The combination with a calling high frequency station and a plurality of other high frequency stations, of means at the calling high frequency station for producing and transmitting a common high frequency wave, means at each of said other stations responsive to said common high frequency wave and differently controlled by said calling station over said common high frequency wave to enable the selection of a particular one of said other stations, and means at the calling station and the selected station made operative upon the completion of the selecting operation for causing each of said two stations to produce and utilize for communicating purposes a wave other than said common high frequency wave.

38. The combination with a plurality of stations, of means at each station for producing and responding to a calling high frequency wave and communicating high frequency waves, means controlled by one of said stations in calling for selecting a particular one of said other stations through the medium of said calling wave, and means made operative upon the completion of said selecting operation for establishing communicating relations between the calling station and the selected station through the medium of said communicating waves.

39. The combination with a plurality of stations each having means for producing and responding to a calling high frequency wave and a plurality of communicating high frequency waves, of means made operative by one of said stations in calling for selecting for use a particular one of said communicating waves, means controlled by said calling station through the medium of said calling wave for selecting a particular one of the other stations, and means made operative upon the completion of said last mentioned selecting operation for bringing the calling station and the selected station into operative relation through the medium of said selected communicating wave.

40. The combination with a plurality of stations, of means at each station for producing and utilizing a common high frequency wave and a plurality of individual high frequency waves to be used with waves from other stations in pairs, means made operative by one of said stations in calling for selecting an available pair of individual high frequency waves for communicating purposes, and means controlled through the medium of said common high frequency wave for causing a second station to select the same pair of high frequency waves to establish communicating relation with said first station.

41. The combination with a plurality of stations, of means at each station for producing and utilizing a common high frequency wave and a plurality of individual high frequency waves to be used with waves from other stations in pairs, means made operative by one of said stations in calling for appropriating an available pair of individual high frequency waves, means operated from the calling station through the medium of said common high frequency wave for causing a second station to select the same pair of individual high frequency waves, and communicating apparatus at said stations brought into operative relation through the medium of said selected pair of waves.

42. The combination with a calling station and a called station, of means at the calling station for producing and transmitting a common high frequency wave, means at the called station responsive to said common high frequency wave, and means made operative in the response of said called station to said common high frequency wave for causing the production and utilization of another high frequency wave for establishing operative relation between said calling station and said called station.

43. The combination with a calling station and a called station, of means at each station for producing and receiving a calling high frequency wave and the respective individual waves of a plurality of pairs of communicating high frequency waves any pair of which may be used for communicating between the calling station and the called station, means at the calling station for selecting a particular pair of said communicating waves, and means at the called station controlled by the calling station over said calling high frequency wave for placing the called station in condition to employ the pair of communicating high frequency waves selected for employment by the calling station.

44. The combination with a calling station and a called station, each having means for producing and utilizing a plurality of high frequency waves, of means at said stations for utilizing one of said waves for controlling preliminary switching operations, and means automatically made operative at said stations upon the completion of said preliminary switching operations for discontinuing the employment of said wave and establishing communicating relation between said stations over another one of said waves.

45. The combination with a plurality of stations, of means at each station for producing and responding to a calling high frequency wave and the respective individual waves of a plurality of pairs of communicating high frequency waves, said stations

- being normally operatively associated by way of said calling wave, means at said stations for effecting preliminary switching operations at a calling and a called station
- 5 thereof through the medium of said calling high frequency wave, means for withdrawing said calling wave and establishing a communicating condition between said stations through the medium of one of
- 10 said pairs of communicating waves, and means for automatically terminating the operative relation by way of said communicating wave and returning to said calling wave when the communicating condition
- 15 between said stations is ended.
46. The combination with a plurality of stations, of means at each station for producing and responding to a calling high frequency wave and a communicating high frequency wave, said stations being normally responsive to said calling wave, means controlled by one of said stations in calling for selecting a particular one of said other stations through the medium of said calling
- 20 wave, means including an arrangement of control circuits made operative upon the completion of said selecting operation for making said selected station unresponsive to said calling wave and establishing communicating relation between the calling and selected stations through the medium of said communicating wave, and means made operative upon the release of the connection at the calling station for making said selected
- 25 station unresponsive to said communicating wave and responsive to said calling wave.
47. The combination with a plurality of stations, of means at each station for producing and responding to a calling wave and a plurality of communicating waves, means made operative by one of said stations in calling for selecting an idle one of said communicating waves, impulse transmitting mechanism at said calling station
- 30 made operative upon the selection of an idle communicating wave for transmitting impulses over said calling wave, and automatic switching mechanism at one of said other stations controlled by said transmitted impulses.
48. The combination with a plurality of radio stations, of means at each station for producing and responding to a calling wave and a plurality of communicating waves, means made operative by a calling one of said stations for selecting an idle one of said communicating waves, impulse mechanism at said calling station operated upon the selection of an
- 35 idle one of said communicating waves to send out impulses over said calling wave, station-selecting switches at the various other stations for selecting a particular one of said stations in accordance with the impulses sent out, means at the selected sta-
- tion made operative upon the selection of the station for sending an impulse over said calling wave, impulse transmitting mechanism at the calling station made operative by the receipt of said impulse from
- 40 the called station for sending out a series of groups of impulses over said calling wave, local lines at the selected station, and selecting switch mechanism at said selected station selectively responsive to said series of groups of impulses and acting to cause said station to become tuned to the communicating wave selected by the calling station and to become extended to a particular one of said local lines.
49. The combination with a plurality of stations, each having means for producing and utilizing a calling high frequency wave and a plurality of communicating high frequency waves, of means made operative at any calling one of said stations for testing for the presence of said calling wave, apparatus made operative by the absence of said calling wave for selecting an idle one of said communicating waves, and means for establishing communication between said calling station and any desired one of the other stations over said selected communicating wave.
50. The combination with a plurality of stations, each having means for producing and utilizing a calling high frequency wave and a plurality of communicating high frequency waves, of means made operative at a calling one of said stations for testing for the presence of said calling wave, means made operative by the absence of said calling wave for establishing communication between said calling station and a desired one of said other stations over one of said communicating waves, and means responsive to the presence of said calling wave for preventing said calling station from establishing communication with another station.
51. The combination with a plurality of stations, each having means for producing and utilizing a calling high frequency wave and for producing one and receiving the other wave of each of a plurality of pairs of communicating high frequency waves, of means made operative at a calling station for testing for the presence of said calling wave, means responsive to the absence of said calling wave for selecting an idle pair of said communicating waves, means at the called station controlled by the calling station through the medium of said calling wave for causing the called station to select the pair of communicating waves selected by the calling station, and means for causing the calling and called stations to discontinue the use of said calling wave and establish communicating relation with each other through the medium of said selected pair of communicating waves.

52. The combination with a plurality of stations, of means at each of said stations for producing and responding to a plurality of high frequency waves any one of which 5 may be used for communication between said station and any other of said stations, means made operative in calling for automatically selecting an idle one of said high frequency waves, means for utilizing the selected wave for communicating with the desired station, and means for preventing the automatic wave-selecting means of any station from operating while said selecting means of any other of said stations is 10 operating.

53. The combination with a plurality of stations, of means at each of said stations for producing and responding to the respective individual waves of a plurality of 20 pairs of high frequency waves less in number than the number of stations, any pair of which waves may be used for communication between any station and any other of said stations, automatically operating 25 means at each of said stations for selecting an idle pair of said waves and employing the same for communication with any desired one of said other stations, and means for preventing said automatically operating 30 means of two or more of said stations from performing their selecting operations at the same time.

54. The combination with a plurality of stations, of means at each station for producing a calling high frequency wave, selecting switch mechanism at each station under the control of said calling wave produced by some other station, and means for preventing the production of said calling wave by any station during the time that the wave is being produced by some other station.

55. The combination with a plurality of stations, of means at each station for producing and responding to a calling high frequency wave and a plurality of communicating high frequency waves, switch apparatus and communicating apparatus at each station adapted to be controlled 45 through the medium respectively of said calling wave and of said communicating waves, and means at each station for preventing that station from producing and utilizing any one of said waves when it 50 is being produced and utilized by other said stations.

56. The combination with a plurality of high frequency trunks, of incoming call receiving mechanism associated with each 60 trunk, a calling station having means for producing and controlling a calling high frequency wave to which said receiving mechanisms of all non-busy high frequency trunks are responsive, local lines associated 65 with each high frequency trunk, and means

for rendering each trunk inaccessible to its associated local lines during the continuance of said calling high frequency wave.

57. The combination with a plurality of high frequency trunks and associated local 70 lines, each trunk having low frequency terminals for connection with local lines and high frequency terminals for connection with other high frequency trunks, of a calling high frequency trunk having means for 75 producing and controlling a calling high frequency wave, high frequency responsive switching means associated with the high frequency terminals of each trunk responsive to said calling wave when the trunk is 80 not in use, and means controlled thereby for preventing the extension of the associated local lines to the idle trunks by way of their low frequency terminals during the 85 continuance of said calling wave.

58. The combination with a plurality of high frequency trunks each having low frequency terminals and high frequency terminals, of local lines associated with each trunk and adapted for connection with 90 said trunk through said low frequency terminals, a calling station having means for producing and controlling a calling high frequency wave, high frequency responsive switching mechanism associated with the 95 high frequency terminals of each trunk and controlled by said high frequency wave to select a particular one of said trunks and exclude the others, and means controlled by said switching mechanism for producing a 100 busy test condition upon the low frequency terminals of all said excluded trunks during the receipt of said calling wave from said calling station.

59. The combination with a calling station and a called station, each provided with means for producing and responding to a calling high frequency wave, the responding means of both stations being normally operative and the producing means normally 105 inoperative, of means for rendering the producing means of the calling station operative to cause the operation of the responding means of the called station, and means including apparatus at each station for simultaneously rendering operative the producing means of the called station and the responding means of the calling station to 110 send a return signal from the called to the calling station.

60. The combination with a calling station and a called station, each having means for producing and responding to a calling high frequency wave, of call sending and call receiving mechanism at each station, 115 means for rendering operative the call sending mechanism of the calling station and the call receiving mechanism of the called station during the transmission of the calling signals, and means at each station auto- 120

5 matically operated upon the completion of the signal sending operation for making operative the call receiving mechanism of the calling station and the call sending mechanism of the called station to produce a return signal from the called station to the calling station.

10 61. The combination with a plurality of high frequency stations of station selecting apparatus at each station, means at each station for producing a calling high frequency wave to which the station selecting apparatuses of the other non-busy stations are responsive, controlling means at a calling one 15 of said stations for controlling said calling wave to effect the selection of a particular one of the other stations, release controlling mechanism at the calling station automatically set for operation a predetermined interval after the completion of the selecting 20 operation, and means actuated in the selection of the called station for preventing the operation of said release-controlling mechanism.

25 62. The combination with a calling station and a called station, each station being provided with means for producing and responding to a calling high frequency wave, of means operating through the medium 30 of the calling wave produced at the calling station for selecting the called station, means at the calling station set upon the completion of the selecting operation for producing a busy indication, and means at the 35 called station controlled through the medium of the wave produced at that station and made operative upon the completion of the selecting operation for preventing the production of the busy signal at the calling 40 station.

45 63. The combination with a plurality of stations, each having means for producing and responding to a plurality of high frequency waves of different character, of means for employing a wave of one character for controlling preliminary switching operations at a calling station and at the station that is being called, means automatically made operative at the calling and called 50 stations upon the completion of said preliminary switching operations for discontinuing the employment of said wave and establishing communicating relation between said stations over another one of said waves, means at the calling station made operative 55 a predetermined interval after the completion of said preliminary switching operations for producing a busy indication and preventing the establishment of said communicating relation, and means made operative by the called station through the medium of said other wave upon the discontinuation of the wave of said one character for preventing the production of said busy 60 indication at said station and permitting the

establishment of the communicating relation.

64. The combination with a plurality of stations, of means at each station for producing a plurality of high frequency waves any one of which may be employed by any calling station for establishing communicating relation with a desired one of said other stations, means for automatically selecting for use an idle one of said high frequency waves, and means responsive to the failure of said selecting means to select an idle high frequency wave for operating busy indicating mechanism at the calling station.

65. In a communicating system, the combination with a line, of a plurality of high frequency stations having means for producing and utilizing a plurality of pairs of high frequency waves for communicating between said stations, means controlled over said line for automatically selecting an idle one of said high frequency stations, and means at each of said high frequency stations for testing successively for the presence of the respective waves and for automatically selecting for use one of said pairs of high frequency waves that is not at the time in use.

66. In a communicating system, the combination with a line, of a plurality of high frequency trunks, each trunk having means for producing and utilizing a plurality of high frequency waves, means controlled over said line for automatically selecting an idle one of said high frequency trunks, means for testing for the presence of the respective waves in succession and automatic means for selecting for production and utilization an idle one of said high frequency waves.

67. In a communicating system, the combination with a plurality of lines constituting an exchange, of a plurality of high frequency trunks to which the lines of said exchange have access, means associated with each of said trunks for producing and utilizing a plurality of high frequency waves, means controlled over any of said lines in calling for automatically selecting an idle one of said high frequency trunks, and automatic means made operative upon the selection of an idle trunk for causing said trunk to select for production and utilization an idle one of said high frequency waves.

68. In a signaling system, a line, a plurality of high frequency signaling stations to which said line has access, means at each of said high frequency stations for transmitting and receiving a plurality of high frequency waves for utilization in effecting non-interfering communication with distant similar stations, means controlled over said line for automatically selecting an idle one of said stations, and locally controlled automatically acting means at the selected sta-

tion for thereafter selecting and appropriating for exclusive use an available one of said high frequency waves.

69. A system of communication comprising a telephone exchange and a distant telephone exchange and a high frequency wave communicating system for interconnecting said telephone exchanges said high frequency wave system having means for transmitting and receiving waves of preassigned non-interfering high frequencies any one of which may be used in effecting communication between said exchanges and means controlled at one telephone exchange for automatically selecting for use an idle high frequency wave and thereafter controlling apparatus at the distant telephone exchange by means of the selected high frequency wave.

70. A communicating system comprising a plurality of high frequency channels and low frequency telephone lines adapted to be connected therethrough, means for automatically testing and selecting any available one of said high frequency channels for communicating purposes, means for transmitting a high frequency wave through said selected high frequency channel, switching means controlled by a high frequency wave for selecting a desired low frequency telephone line at a distant point and connecting it to said selected high frequency channel, and means for thereafter controlling the high frequency wave of said selected channel to transmit speech through said high frequency channel and repeat the speech so transmitted into the selected low frequency telephone line.

71. A high frequency signaling system having a number of stations, a plurality of high frequency channels at each station through any one of which any station is adapted to communicate with any other station of the system, means for enabling one of said stations to select an idle one of the other stations, and means for automatically selecting an available high frequency channel for establishing communication between the selecting station and the selected station.

72. In a communicating system, a plurality of stations each having associated communicating apparatus, means at each station for producing and utilizing a plurality of high frequency waves any one of which may be used for communication between said station and any other station of the system, means under the control of a calling one of said stations for selecting a desired one of the other stations, and means for automatically selecting an available high frequency wave for communication between said calling station and said selected station.

73. In a signaling system, two carrier wave stations, apparatus at each station for communicating between said stations thru

the medium of any one of a plurality of waves of different characteristic frequencies, and means acting automatically in response to the initiation of a call for selecting and appropriating for use between said stations a wave of a particular one of said characteristic frequencies.

74. In a communicating system, the combination with two high frequency stations each having communicating apparatus and controlling apparatus, of means at each station, for producing and responding to a high frequency wave, said responding means including means for deriving from received waves a wave of an intermediate frequency, and for making said intermediate frequency operative to control alternatively said controlling apparatus and said communicating apparatus.

75. In a signaling system, two carrier wave stations, apparatus at each station for communicating between said stations through the medium of any one of a plurality of waves of different characteristic frequencies, means at one station for appropriating for use a wave of a particular one of said characteristic frequencies, and means at the other station actuated in response to the taking for use of such wave at the said one station for automatically conditioning for use the apparatus at the said other station, employed for communicating thru the medium of the wave of the appropriated frequency.

76. In a high frequency communicating system having a plurality of stations, the combination with a plurality of high frequency channels each of which is available for use at each of said stations, of a plurality of trunks at each station each of which is adapted to use any idle one of said channels for communicating with another station, and communicating apparatus at each station adapted for connection with any of said high frequency trunks of the associated station.

77. In a high frequency communicating system having a plurality of stations, the combination with a plurality of high frequency communicating channels available for use at each of said stations, of a plurality of trunks at each of said stations, each of said trunks being provided with means for utilizing any idle one of said communicating channels, communicating apparatus at each station adapted to be connected with any of the associated trunks, and means for automatically identifying the trunk with which said communicating apparatus is to be connected.

78. In a high frequency communicating system, the combination with a plurality of stations each having associated communicating apparatus and a plurality of trunks, of a plurality of high frequency communicating channels available for use at each of

said stations, and means at said high frequency stations for bringing the communicating apparatus of any two of said stations into operative relation through the medium 5 of any of the associated trunks and any of said high frequency communicating channels.

79. In a high frequency communicating system having a plurality of stations, the 10 combination with a plurality of high frequency communicating channels available for use at each of said stations, of a plurality of trunks at each of said stations, communicating apparatus at each station, means 15 for establishing connection between said communicating apparatus and an available one of said associated trunks, and means controlled locally at a station for automatically selecting an idle one of said communicating channels and bringing the selected 20 trunk into operative relation therewith for communicating with the desired distant station.

80. In a signaling system, two stations, 25 means for communicating between said stations by means of any one of a plurality of waves of different frequencies, means for automatically determining which wave is to be used for a communication, and means 30 controlled by the wave-determining means for setting the communicating means of both of said stations to employ said wave for communicating with each other.

81. In a signaling system, two stations, a 35 plurality of high frequency channels to which one station has access for transmitting and the other station has access for receiving, means at one station to select a particular high frequency channel and to call 40 the other station, means at the other station to identify and seize the selected channel, and means for transmitting and receiving signals over the selected channel.

82. In a signaling system, two stations, a 45 plurality of high frequency wave channels common to said two stations, means at one station to select for use a particular one of said channels, and to designate the selected channel to the other station, means controlled by said designating means to bring 50 the other station into operative relation with the selected channel, and means for signaling between said stations through the selected channel.

83. In a signaling system, two radio stations, a receiving and a transmitting antenna at one station, means controlled from the other station for tuning the receiving antenna to a desired frequency, and means 60 for automatically tuning said transmitting antenna to a frequency dependent on the frequency to which the receiving antenna is tuned.

84. In a signaling system, a high fre-

quency wave channel, a plurality of stations 65 to which said channel is accessible, means for transmitting impulses of said high frequency wave to call a desired one of said stations, means for thereafter transmitting signals by means of high frequency waves, 70 and means operative only at the station selected by said impulses to respond to said signals.

85. In a signaling system, a high frequency wave channel, a plurality of stations 75 to which said channel is accessible, means to produce stations-designating variations in said wave to select a particular one of said stations and for thereafter producing variations of said wave to indicate other designations, and means only at the station selected 80 by said stations-designating variations made operative by said variations for receiving the other designations.

86. In a signaling system, means to send 85 a wave of a definite frequency and to produce control impulses in said wave, a plurality of stations having impulse-driven apparatus thereat, and means controlled by certain of said wave impulses for selecting a 90 desired station and for placing the apparatus of only that station under control of subsequent impulses of said wave.

87. In a signaling system, a station having a two-way low-frequency signaling terminal, 95 and a high frequency transmitting terminal and a high frequency receiving terminal operatively associated with said signaling terminal, said high frequency terminals each being arranged to operate at any one of a 100 plurality of high frequencies, and means responsive to a wave of any of said receiving frequencies received at said receiving terminal for causing said transmitting terminal to transmit a particular wave of a frequency 105 dependent upon the frequency of the received wave.

88. In a signaling system, stations, means for generating a plurality of waves of different frequencies for use interchangeably 110 for non-interfering communications between different ones of said stations, means to generate a common wave to which all stations are normally responsive, and means controlled by said common wave for selecting 115 out one of said stations and for causing it to employ a particular one of said waves to communicate with a certain other of said stations.

89. In a carrier telephone system, a carrier wave station, a plurality of carrier telephone channels terminating in said station, a plurality of ordinary telephone lines terminating at said station, an automatic switch for operatively associating a telephone line with one of said channels, a testing circuit for said channels, and means controlled by said testing circuit for causing

said switch to pass over busy channels and stop in position to associate a said telephone line with an idle channel.

90. In a carrier telephone system, a carrier wave station, a plurality of carrier telephone channels terminating in said station, a plurality of ordinary telephone lines terminating in said station, each of said lines terminating in two branches, one outgoing and the other incoming, said channels being paired, the channels of each pair being arranged for transmission in opposite directions, an automatic switch for operatively associating the two branches of a telephone line with the respective channels of any pair of channels, a testing circuit for said pairs of channels, and means controlled by said testing circuit for causing said switch to pass over busy channels and to remain in position to associate the outgoing branch of a telephone line with one of the channels of an idle pair and the incoming branch of the same telephone line with the other channel of said pair.
91. In a carrier telephone system, stations, a plurality of carrier wave channels, each having terminals appearing in said stations, a testing circuit in each of said stations for said channels, means controlled by a testing circuit in any station for finding and seizing an idle channel and means responsive to such seizure for making the terminals of said seized channel test busy in the other stations.
92. In a signaling system, two stations, a plurality of signaling channels employing waves of distinctive frequencies for carrying on communications between said stations, and means controlled from one of the stations and including a separate channel for selectively identifying at the other station an individual signaling channel.
93. In a signaling system, two stations, a plurality of signaling channels employing different frequencies for transmitting signals between said stations, a separate calling channel, and means to indicate over said calling channel the particular channel to be used in communicating between said stations.
94. In a signaling system, two stations, a

plurality of signaling channels employing waves of distinctive frequencies for carrying on communications between said stations, and means controlled from one of the stations and including a separate channel for selectively conditioning for use the apparatus of any of said signaling channels at the other station.

95. In a signaling system, stations greater in number than two, apparatus for producing waves of a plurality of frequencies, means for enabling any of said stations to use the waves of said different frequencies in common for communicating with one another, and means including the apparatus for producing one of said waves for selectively calling the respective stations.

96. In a signaling system, stations greater in number than two, means at said stations including wave transmitting and receiving apparatus arranged to enable waves of the same distinctive frequencies to be used by said stations in common for carrying on non-interfering communications between any of said stations, and means including wave transmitting and receiving apparatus employing a wave of a separate frequency for enabling any station to call any other station selectively.

97. In a carrier wave communicating system, an initiating station and a distant station, a high frequency wave transmitting channel therebetween, a selective switch at the distant station, means at the initiating station operating through said channel for controlling the actuation of said switch, and means controlled in the actuation of said switch for controlling said first means.

98. In a radio signaling system comprising a plurality of stations arranged for intercommunication on a plurality of carrier frequencies, means for establishing communication with a plurality of stations on any given carrier frequency and a selective calling means for selecting any one of said plurality of stations.

In witness whereof, we hereunto subscribe our names this 26th day of April A. D., 1920.

EDWIN H. SMYTHE.
SAMUEL B. WILLIAMS, Jr.
